UNITED STATES PATENT OFFICE

FREDERICK M. FURBER, DECEASED, LATE OF REVERE, MASSACHUSETTS, BY SAMUEL R. CUTLER, ADMINISTRATOR, OF REVERE, MASSACHUSETTS, ASSIGNOR TO UNITED SHOE MACHINERY CORPORATION, OF PATERSON, NEW JERSEY, A CORPORATION OF NEW JERSEY

SHOE MACHINE

Application filed August 16, 1926. Serial No. 129,469.

The present invention relates to machines for assembling such articles as shoe-portions, and particularly concerns apparatus of the character of that disclosed in an application filed in the name of Frederick M. Furber, deceased, on June 15, 1921, for an assembling machine, this application bearing the Serial Number 477,709. On November 13, 1928, said application became Patent No. 1,691,277. 5 By this machine there are successively brought together from their respective containers upon a support, shoe-portions, which may include a sole, an adhesive liquid, a piece for stiffening the shank of such sole and a 10 piece occupying the space over an insole between the inner edges of the welt of a shoe-upper, and thereafter uniting these assembled portions by pressure to furnish a complete shoe-bottom unit.

20 A feature of the invention involves the simultaneous variation of the relation to associated parts of a plurality of elements which co-operate with the work. These elements may be located at different operating 25 positions, and may include, for example, an adjusting member for a shoe-portion-engaging projection on the support, container-walls and a gage-wall at the sole-supplying position, a valve-controlling member at the 30 adhesive-applying position, shoe-portion-transferring devices at the shank-piece-supplying position and that at which the finished work is removed from the support, and a container-wall at the filler-piece position.

35 In whatever combination these variations are effected, they are preferably made through connections to the respective elements from a member arranged to be set by the operator in accordance with shoe sizes. By this interconnection of parts of different operating mechanisms to a common controlling device, their variation is greatly facilitated, and perfect co-ordination assured. Other simultaneous adjustments may be provided for, 40 as of elements to correspond to right and left shoe-portions. In the present instance, these include a wall of the container for filler-pieces, and a member for correcting the location of the soles on the support before the 45 filler-pieces are supplied thereto. This last

mentioned or sole-locating operation is in itself a feature of much significance.

Another feature of the invention has to do with the guarding against the production by the machine of imperfect work. In this connection, warning is given the operator of a lack of a proper supply of work-portions in their containers, there being shown, in the present instance, stack-testing means for the soles, shank-pieces, and filler-pieces. These testing means control the operation of the machine, as through a particular operating mechanism, which may be that for feeding and transferring soles. The thus-governed mechanism, in the present embodiment of the invention, is stopped, until again put in action after the operator has renewed the supply. So, too, the absence of a shoe-portion from a transferring device, which may have failed to grasp or retain it, similarly stops an operating mechanism. Such a mechanism at the filler-piece position is shown as controlled from the shank-piece-transferring device.

55 Several of the mechanisms in the apparatus, as those for governing the operating mechanism at the sole-supplying position, for testing the stack in the container at this position, for adjusting the soles at the filler-piece-supplying position and there applying an assembling force to the portions, and for advancing successively the receptacles which are to receive the completed soles, are preferably actuated by fluid-pressure. Features 60 of the invention concern the applying of this pressure in an effective manner, and, in certain connections, as for the assembling, only after the necessary previous operations upon the work have been performed. This insuring of the proper sequential operation, as the 65 result of control of the mechanisms by those operating earlier in the cycle, is believed to be novel, regardless of whether or not a fluid furnishes the actuating medium.

70 Still other features of the invention may be found in the provision of effective containers for the shoe-portions at various positions, said containers being readily and accurately adjustable and reliable mechanisms for delivering the portions from the containers to 75

the support and the completed work from said support to the receptacles which are to hold it.

Other features will appear from the following description and will be pointed out in the appended claims.

One of the many embodiments which this improved machine may assume is illustrated in the accompanying drawings, in which

10 Figs. 1 and 2 are broken top plan views, these, when taken together, showing in a diagrammatic manner the entire apparatus;

15 Fig. 3 is a horizontal section, illustrating particularly the gearing for driving the turret and the operating mechanisms at the various positions;

20 Fig. 4 illustrates, generally in side elevation, a portion of the turret and one of the work-supports, with parts broken away;

25 Fig. 5 is a top plan view of mechanism at the first operating position at which soles are supplied to the supports, together with a work-support in co-operation therewith;

30 Fig. 6 is a detail, similarly shown, of a cam member which serves to set the work-engaging projections of the supports upon the turret;

35 Fig. 7 is a side elevation of mechanism at the first position;

33 Fig. 8 is an end elevation thereof;

Fig. 9 shows in perspective portions of the sole-feeding mechanism;

33 Figs. 10 and 11 illustrate, in vertical longitudinal section, the sole-magazine and associated feeding mechanism, the latter being in different operating relations in the two views;

Fig. 12 is a vertical sectional detail through the transferring device at the first position;

35 Figs. 13 and 14 are enlarged transverse sections through the sole-feeding mechanism, with the transferring mechanism in co-operation therewith, said transferring mechanism being respectively in its approaching and sole-engaging relations in the two views;

Fig. 15 is an enlarged broken end elevation of the mechanism for controlling the operations at the first position;

35 Fig. 16 illustrates the same elements in broken side elevation;

Fig. 17 is a broken side elevation of the cement-applying mechanism at the second position;

35 Fig. 18 is a representation of a cemented sole, this being a top plan view;

Fig. 19 is a vertical transverse section through the cement-applying nozzle, valve and its controlling elements;

35 Figs. 20, 21 and 22 show in side elevation successive positions of the elements for governing the cement-valve;

35 Fig. 23 is a detail in top plan view of the driving mechanism for the cement-applying mechanism and the turret;

Fig. 24 is a vertical section on the line XXIV—XXIV of Fig. 23;

70 Fig. 25 is a horizontal sectional detail through the driving mechanism on the line XXV—XXV of Fig. 17;

Fig. 26 shows in broken side elevation the shank-supplying mechanism at the third operating position;

75 Fig. 27 is a horizontal sectional detail of the valve at the third position for controlling the mechanism at the fourth position;

Fig. 28 is a vertical section on the line XXVIII—XXVIII of Fig. 30;

80 Fig. 29 represents diagrammatically the fluid-pressure system of the apparatus;

Fig. 30 is a top plan view of the shank-piece-holding and feeding elements;

85 Fig. 31 is a broken top plan view of the testing mechanism associated with the shank-piece-magazine;

Fig. 32 illustrates in perspective a portion of the shank-piece-feeding disk;

90 Fig. 33 is a detail in enlarged side elevation of a portion of the controlling mechanism for the fourth operating position, this being associated with the transferring mechanism at the third position;

95 Fig. 34 shows in broken side elevation the controlling elements at the fourth position acted upon by the device illustrated in Fig. 33;

Fig. 35 is a horizontal section on the line XXXV—XXXV of Fig. 34;

100 Fig. 36 illustrates in broken side elevation the filler-piece-applying and work-pressing mechanisms at the fourth operating position;

105 Fig. 37 is an enlarged side elevation of the filler-piece-applying and pressure mechanisms at this position, parts being broken away;

Fig. 38 is an elevation of the opposite side of the elements appearing in Fig. 37;

110 Fig. 39 is a broken elevation of the upper portion of the pressure-cylinder at the fourth position;

Fig. 40 is a horizontal section taken above the pressure mechanism;

115 Fig. 41 is an irregular vertical section at the toe-end of the filler-piece-magazine;

Fig. 42 is a top plan view of the valve mechanism controlled by the filler-piece feed-slide;

120 Fig. 43 is a transverse section on the line XLIII—XLIII of Fig. 37;

Fig. 44 shows a portion of the adjusting connections between various positions controlled by the operator;

125 Fig. 45 illustrates in side elevation the work-removing mechanism at the fifth operating position, together with a receptacle for the work;

Fig. 46 is a broken top plan view of a portion of the transferring mechanism at this position;

Fig. 47 is a longitudinal vertical section through the advancing mechanism for the receptacles;

Fig. 48 is a broken top plan view of a portion of the advancing mechanism;

Fig. 49 is a sectional detail on the line XLIX—XLIX of Fig. 47;

Fig. 50 is an enlarged transverse section on the line L—L of Fig. 47;

Fig. 51 is a broken side elevation of a support at the fifth position, together with certain elements at such position for controlling parts of the support and for governing the application of fluid-pressure;

Fig. 52 illustrates in end elevation the parts appearing in Fig. 51; and

Fig. 53 is a diagram of the adjusting connections joining the first operating position with mechanisms thereat and at other positions.

There will first be described the work-supporting turret with its driving mechanism, together with a general statement of the relation thereto of the co-operating mechanisms for acting upon the work, this being followed by detailed descriptions of each of these mechanisms, taken in the order in which they act to produce a complete article, and there being a concluding outline of the operation of the entire machine.

Turret, general arrangement of operating mechanisms and driving mechanism therefor—(Figures 1 to 4, inclusive, 17, 23, 24 and 25)

Rising from the center of a base 60 (Fig. 17) is a tubular standard 61, here illustrated as being made up of a plurality of sections, one upon the other, and having arranged to turn about the lower section a sleeve 62, which is stepped at the bottom upon an anti-friction bearing 63. Radiating symmetrically with respect to their angular arrangement in a horizontal plane, are arms 64 bolted to the sleeve, there being five of these arms shown. Carried upon the upper surface of each arm is a work-support, furnished by a block 65. These work-supports upon each of the arms may be identical as to their construction and directly associated elements, so that but one of these need be described in detail. The upper face of the support 65 closely approaches to the contour of the objects to be operated upon, in the present instance these consisting of soles for shoes, of which one is illustrated at S (see particularly Fig. 4 of the drawings). Generally, it may be said that the form of the supporting surface represents an approximate mean between the right and left soles of all the sizes to be applied to the support.

To fix a sole in predetermined position longitudinally of the support, some such locating device as a pin 66 is caused to project through said support, being carried upon the

arm 64 and arranged to move in a longitudinal slot in the support. This pin may enter an opening o (Fig. 5) situated near the transverse center and close to the rear edge of the sole. In the present instance, the soles operated upon as shown are of such length that each will terminate upon a shoe beneath the associated heel and in proximity to the breast thereof, these being known as short soles.

Since it is desired that, for all sizes of soles, some point between the heel and toe-ends shall have the same relation to the support, the pin 66 is adjustable longitudinally of the arm, it rising vertically from a slide 67 movable

in ways thereon and being urged normally outward by a spring 68 located in a recess in the arm and bearing against the inner end of the slide. The movement of the pin with its slide to the correct position to receive the particular length of the sole to be operated upon is effected by setting or actuating means situated between the first and last operating positions of the support, this contacting with a roll 70 rotatably mounted in a horizontal plane at the outer extremity of the slide. The adjustment of the pin 66 through the action of the setting means upon this roll will hereinafter be described in detail. When adjusted, the slide and pin are temporarily locked by a lever 72 pivoted upon the arm and having a wedge-shaped cam-portion 74 entering a groove in the under side of the slide. A spring 76 so swings the lever upon its fulcrum that the cam-portion normally acts to hold the slide against outward movement by the spring 68. It is released by upward pressure upon a roll 78 rotatable upon an outwardly extending arm of the lever 72, and governed by a contact device, the action of which will be discussed in connection with that acting upon the roll 70.

When a sole rests upon the upper surface of a support with its heel-end located by the pin and its toe-end adjacent to the inner extremity of the support, it is engaged by a retaining device, which holds it against rising, and resists lateral movement during the performance of the various operations. The like devices co-operating with the supports each includes a substantially vertical lever 80 fulcrumed upon the lower portion of the supporting arm 64. Secured to the upper extremity of this lever by a screw 82 is a member 84 having at its outer side a contact-surface 86 inclined downwardly and away from the support, which, when pressed against the end of a sole toward the pin 66, forces this upon the supporting surface, exerting such frictional engagement as to hold it against accidental swinging about the pin. The surface 86 is shown as broadened laterally (Figs. 1 and 2) so that there will be proper engagement with the end of a sole, whether this be left or right, and therefore

70

75

80

85

90

95

100

105

110

115

120

125

130

differently disposed transversely of the supporting surface. When the pressure of the member 84 comes against the inner end of the sole, it may tend to buckle it, so the outer extremity may be raised from the pin 66. To prevent such displacement, the heel-end of the sole is retained against vertical movement by the hooked end 88 of a lever 90 fulcrumed upon the upper face of the arm 64 beneath the support and having an arm with an inclined end 92 lying in the path of movement of the lever 80. A spring 94, connecting the lever and arm, exerts its tension to draw the hooked end 88 over the sole-supporting surface. When the lever 80 is forced back in the manner described below, its upper end, striking the inclined portion 92 of the lever 90, swings the latter upon its fulcrum, and removes the hooked end 88 from above the support. This provides for the deposit and removal of a sole. Upon inward movement of the lever 80 to bring its contact-surface 86 against the sole placed upon the support, this lever leaves the end 92 of the lever 90, which, 25 acted upon by its spring 94, carries the retaining hook 88 above the sole, this position being attained just before contact of the surface 86. The sole is thereby positively held against upward movement. To bring about the normal engagement of the retaining surface 86 with a sole on the support and establish effective engagement, whatever the sole-size may be, a spring 98 connects the lever 80 and the lower portion of the arm 64. 30 The retaining member 84 may be latched out of engagement with the sole by a lever 100 fulcrumed upon lugs depending from the arm beneath the support, and recessed at its end 102 to receive a stud 104 projecting horizontally from the side of the lever 80. The opposite or outer end of the latching lever 100 is engaged by a contact-head 106 carried upon a vertical member or pin 108 mounted to slide on the arm and movable through an 35 opening near the center of the support, this preferably being in proximity to the lowest point of the curved tread-surface of the sole. The length of the pin is such that it may, when there is no sole upon the support, be projected above the surface of the latter. 40 When the pin 108 is held down by a sole, as is illustrated in Fig. 4, the latching depression 102 of the lever 100 is maintained above the co-operating stud 104, so the spring 98 45 may exert its tension to draw the contact-surface 86 into engagement with the toe-end of the supported sole. Engaging a stud extending across the head 106 of the pin is a forked arm of a bell-crank lever 112 fulcrumed beneath the upper portion of the arm 64. A spring 113, joining the inner end of the lever 112 to the arm 64, may swing to opposite sides of the axis of the fulcrum. When 50 above this axis, it holds the pin 108 raised 55 above the surface of the support 65. When

below the axis, it maintains said pin lowered with its upper extremity beneath the supporting surface. The other arm of the lever 112 has a fork acting upon a slide 114 mounted to move horizontally in the arm. Upon the outer end of the slide, a roll 116 is rotatable, this roll exercising a controlling function at various operating positions. In the first position, on account of the absence of a sole when the support 65 arrives at this point, the pin 108 is elevated, and the roll 116, governed by its connection thereto, lies in a vertical plane differing from that which it occupies at the other four operating positions, at which a sole is upon the support and has depressed the pin. Because of this relation, the bringing into action of the operating mechanisms at the positions between and including the second and fourth may be prevented unless a sole has been properly applied to the support at the first position. This will be made clearer as the description progresses. The lever 80 may be released from its latch 100 by the contact of a roll 118 on a laterally extending arm with a fixed element, which will be described in connection with the fifth operating position. 60

It will be seen that the rotatable sleeve 62, with its radial arms 64 and the supports 65 carried thereby, form a turret upon which a plurality of pieces of work may be subjected simultaneously to different operations, and said turret rotated step by step to bring the supports to the positions previously occupied by companion supports, to be there subjected to other operations until a complete cycle of the machine has been effected. To permit these various operations to be performed, there are arranged about the turret, they being separated by angles corresponding to those between the arms 64, five mechanisms occupying positions designated as A, B, C, D and E, these being most clearly illustrated as to their relation in Figs. 1 and 2 of the drawings. In the present machine, at position A, the soles S, preferably previously molded to a form adapting them for application to the bottom of a lasted shoe, are transferred one by one from a container or magazine, and applied to successive supports 65. Having been fixed upon a support, as hereinbefore indicated, the sole is conveyed thereby to position B, at which a portion of its upper surface receives a coating of an adhesive fluid. Then, upon transfer to position C, a stiffener or shank-piece s is lifted from a container or magazine, and laid upon the coated area. Further movement to position D taking place, a filler-piece f of sheet-material, designed to occupy the space over the forepart of the insole of a lasted shoe between the drawn-over edges of the upper, is taken from a container, placed over the shank-piece, and the adjacent surfaces of the three assembled elements pressed firmly 100 105 110 115 120 125 130

together to unite them by the adhesive. Finally, at position E, the thus-completed composite sole is removed from its support, and deposited in a receptacle ready for utilization elsewhere.

To impart the desired intermittent rotation to the turret, and to furnish power for the mechanisms at the operating positions, the driving mechanisms best illustrated in Figs. 3, 17, 23, 24 and 25 may be employed. Mounted upon the base is a motor 130 (Fig. 3). This, through its shaft 132, rotates a worm 134 meshing with a worm-wheel 136 carried upon the periphery of a casing 138 turning about a shaft 140 journaled in a vertical position in the base. The casing carries, rotatable within it, pinions 142, 144 of a planetary system (Fig. 17), they respectively engaging a fixed pinion 146 carried upon a sleeve 147 surrounding the shaft 140, and a pinion 148 fast upon the shaft 140. This last-mentioned pinion contains more teeth than the fixed pinion, resulting in the transmission through the planetary system from the worm-gearing of a much reduced rate of rotation to the shaft 140. Secured upon this shaft 140 is a driving element 150 of a Geneva stop-movement (see particularly Figs. 24 and 25), the driven element 152 of the stop-movement being rotatable about a spindle 154 secured in the base parallel to the shaft 140. Turning about the spindle 154 with the member 152 is a gear 156 meshing with a gear 158 upon the sleeve 62 to cause the rotation of the turret. The effect of this whole chain of gearing is to transmit motion from the motor-shaft 132 to the turret at an extremely low speed-ratio. Upon the shaft 140 is secured a gear 155 engaging a pinion 157 loose upon the spindle 154. From this pinion 157, power is delivered to the operating mechanism at position B, as will be explained later. The effect of the elements 150 and 152 of the Geneva stop-movement is to impart to the turret, through the gearing 156 and 158, rotation with intermediate periods of rest. As the mechanism is illustrated, this produces movement of the turret for an interval one-half that during which it rests. This enables the operating mechanisms associated with the turret to act at each of the positions for a predetermined time, and the turret to then be rotated during a less time, to bring the supports to the succeeding positions. The Geneva movement is of peculiar utility in the present connection, because it permits a gradual starting and stopping, without subjecting the elements to strain. In addition to driving the turret and operating the mechanism at position B from shaft 140, power is transmitted to positions A and C from said shaft respectively through sprocket-gearing 160 and 162 and bevel-gearing 161 and 163. From position A, the mechanism at position E is driven through sprocket-gearing

164 and bevel-gearing 165, while position D receives power from position E by way of sprocket-gearing 166 and bevel-gearing 167.

Operating position A—sole-supplying mechanism—(Figures 5 to 16, inclusive) 70

Rising from the base of the machine is a standard 200, located in alignment with one of the positions at which the work-supports are stopped by the driving mechanism, and having at its upper extremity a container or magazine 199 for the soles S. This container includes a supporting table 201 (Fig. 5) extending horizontally at the top of the support and having a laterally projecting portion, over which the soles are fed and upon which they await transfer to the traveling supports 65. Projecting vertically above the table are an end container-wall 202 and opposite side walls 204 and 206, together furnishing the sides of the magazine. The first-mentioned wall is secured to standards 208, 208 rising from the outer corners of the table, this wall 202 generally paralleling the longitudinal axis of the contained soles and being fixed in position, while the walls 204 and 206 cooperate, respectively, with the heel and toe-ends and are simultaneously adjustable toward and from each other to maintain the longitudinal centers of contained soles of different sizes in approximately the same relation to the table. The wall 204 is shown as of U-form, and is fixed to a frame 210 supported for horizontal movement by a lower rod 212 passing through both standards 208, and to an upper rod 214 guided only in the standard nearest the wall (Fig. 7). Mounted to reciprocate at the upper portion of the opposite standard is a rod 216, to which is fixed the wall 206 by a frame similar to that which carries the wall 204. The rod 216 is further guided by a bracket 218 rising from a member 220 projecting from the standard 208. Fulcrumed at the outer end of the bracket 220 is an equal-armed lever 222, articulated at its opposite extremities to the rods 212 and 216, respectively. To impart movement to the end walls of the magazine, and to adjust elements at the other stations, together with the controlling means for the pin 66, as will later appear, there are formed beneath the table ways to receive a slide 224 (Fig. 8), at the under side of which is carried an outwardly and upwardly extending arm 226, the end of which is secured to the rod 212. Arranged to turn in horizontal bearings in the slide is a spindle 228 (Figs. 13 and 14), the inner end of which is threaded at 230 into a lug at the under side of the table. At the outer end of the spindle, convenient for manipulation by the operator, is a wheel 232 (Fig. 7). When this wheel is turned, the slide, held between fixed surfaces upon the spindle, is carried in or out by the threaded engagement of the spindle with the 130

table. This moves the wall 204 to vary its relation to the central axis of the table to accommodate the magazine for the particular length of sole which is to be operated upon.

At the same time, the wall 206 receives movement, imparted to it from the right-hand extremity of the rod 212 by the lever 222, which causes the rod 216 to be oppositely moved through its guides. To facilitate the setting of the end walls and other elements in accordance with the sole-sizes, the slide 224 has a portion 234 (Fig. 5) extending above the table and bearing an index-point in proximity to a scale 236 applied to the table. The graduations of this scale represent successively the sole-sizes of the series for which the machine is to be used, and upon bringing the index-point into registration with any one of these, the magazine and similarly controlled elements are adjusted in the desired manner.

The delivery-side of the magazine may be closed against outward movement in this direction of all save the lowest sole of the contained stack by a vertical gage-bar 238 (Figs. 10 and 11) carried by an arm 240 (Fig. 5) projecting horizontally from a standard 242 rising from one side of the table, the lower end of the bar being spaced from the table by an amount just sufficient to permit the passage of a single sole at the forepart. Since the drag of this end of the gage-bar upon the sole fed beneath it might be excessive were it rigidly held, and thus interfere with delivery, a vertical yield is provided. At the end of the arm 240 is a guide member 241, in ways in which the bar is arranged to slide. At the upper extremity of the bar is a lateral projection 243 extending over and retained against downward movement by a projection 244 from the guide. Rising from the projection 244 is a rod 246 passing through an opening in the bar-projection 242, and surrounding the rod, between the projection and a head or enlargement at the top of said rod, is a helical spring 248. It will be evident that if there is upward pressure produced upon the gage-bar in excess of the resistance offered by the spring 248, said bar will yield and relieve the force opposed to the feeding of the sole which is passing beneath it, while remaining effective in retaining against movement the rest of the stack. The standard 242 carrying the gage-bar is adjustable along ways in the table, being clamped in place by a screw 250 (Fig. 5) passing through a slot in said table. Attached to the standard is a horizontally extending bar 252 bearing a series of width-graduations, co-operating with which is an index-point 254 fixed upon the side of the table. This provides for a ready variation in the size of the magazine to adapt it for the reception of soles of different widths.

The lower convex surfaces of the molded soles which are to be operated upon rest upon

the table 201, while their upwardly curved shank-portions are supported above this level by a shelf 256 projecting beneath the wall 204. On account of the variations of the soles from a horizontal plane, it is desirable to have the lower inner portion of the end wall 204 cut away to insure the free passage of the heel-ends of the soles over the shelf 256, while the foreparts of these soles are being carried under the gage-bar 238. The space through which the heel-ends pass is, however, limited, to avoid displacement from the magazine of the soles a certain height above that to be fed, by a retaining member consisting of a rod 260 mounted to slide vertically in brackets 262 (Fig. 8) projecting from the front of the wall 204, this rod being held against rotation in its supports. At the bottom of the rod is a downwardly and outwardly inclined foot 264, beneath which the delivered soles successively pass. The normal position of the rod is determined by a collar 266 adjustably fixed upon it, so that the lower surface of the foot is in proximity to though not necessarily in engagement with the sole traveling beneath, while the side of the rod retains the soles above it in the stack. If the sole being fed is so distorted that it contacts with the rod, this engagement will be with the under side of the foot. The vertical component of the force exerted upon the inclined surface will cause the rod to be raised in its guides, so that the advance of the delivered sole will not be interfered with, though the remainder of the stack will be held against lateral displacement.

Formed in the top of the table, and extending beneath the magazine substantially at right angles to the longitudinal axis of a support 65 positioned thereat, is a slot 267 (Fig. 5), along which, in ways, is mounted to move a primary sole-feeding or delivering slide 268. This slide has a depending portion 269, upon which are pivoted blocks 270 (Fig. 13) engaged by the forked ends of a lever 271 fulcrumed upon the standard 200. A roll 272 upon the lower extremity of the lever enters a cam-track 273 (Figs. 10 and 11) in a disk 274. This cam-disk is secured upon one extremity of a shaft 275 (Fig. 7) journaled horizontally upon the base 60 and standard 200, and being in sections, its portions being connected to rotate together by a clutch 276. Rising from the table, adjacent to the slot 267 and inclined downwardly from the wall 202, is a support 277 adapted to elevate the inner or rear edge of the lowest sole of the stack in the magazine above the general supporting surface of the table. The opposite or forward edge is thereby lowered, so that, in proximity to the lower extremity of the gage-bar 238, the relation of the upper surface of this sole to the table will be substantially determined by the thickness of the stock, and the ready passage of a sole fed beneath the gage-

bar is provided for, regardless of whether it is a right or a left, and whatever its transverse curvature. Upon the upper surface of the slide 268, near its outer extremity, considering the relation to the central, vertical axis of the apparatus, is a contact member 278 (Fig. 10) provided at its inner end with an overhanging projection 279. This member is longitudinally slotted or divided to permit its passage past the reduced lower end 280 (Fig. 9) of the gage-bar. The height of the contact member is such that its projection will lie near the upper surface of the sole to be fed. In the inner portion of the slot 267, a secondary slide 281 is movable. It is urged toward the primary slide by a spring 282 situated about a rod 283 projecting from the primary slide through an opening in the secondary slide, this spring abutting at its ends against said secondary slide and against a nut threaded upon the end of the rod. The effect of this spring is to urge the slide 281 toward the slide 268. The slide 281 is longitudinally slotted to receive a pivoted contact member 284, the upper edge of which lies at or below the top of the slide, as best appears in Fig. 11 of the drawings, or elevated above the slide, as is shown in Fig. 10. The latter position is brought about by a setting lever 285 fulcrumed at the under side of the slide 281 and having an arm arranged to engage an inclined surface 286 upon the lower edge of the contact member. The other arm of the setting lever has a projection 287, so located that, in the feeding movement of the secondary slide, it will strike the end of an actuating portion 288 projecting from a lever 289 fulcrumed near the lever 271, but which, at this time, is stationary. The lever 285 is thereby turned to raise the contact member, substantially at right angles to the direction of bodily movement. At the inner extreme of its travel, a depending end 290 of the member 284 engages and presses down an upwardly curved extremity of a depressing spring 291 fixed upon an extension from the standard 200. Upon reverse travel of the slide 281, the spring catches and resists the movement of translation of the contact member, causing it to be tilted in a clockwise direction about its pivot to the lowered position of Fig. 11. When elevated, the member 284 serves to grasp with the member 278 a sole for feeding it from the magazine, and, when lowered, frees the sole for the return of the elements to their initial position for another feeding operation.

Conditions may arise in which the soles resist the oscillation of the lever 271 in either direction to such an extent that the feeding elements might be broken. To guard against this, the upper arm of the lever, which is joined to the slide 268, is formed in two sections connected by a friction device indicated at 292. As a result of this, if there is undue resistance

offered to the movement of the lever in either direction, the upper portion of the arm will yield at the friction device, permitting the lower or driving arm to continue in motion under the influence of the cam, without effect upon the feeding mechanism. To restore the lever 271 to its correct driving relation, resetting devices in the form of contact-screws 293 and 294 are provided. If the upper lever-section is displaced to the right (Fig. 10) because of abnormal resistance to its action during the feed-stroke, upon its return, the lug to which it is articulated upon the slide 268 encounters the screw 293, which is threaded through a portion of the table. This screw may be so adjusted that, at the termination of the oscillation of the lever in this direction by the cam, the angular relation between the two arms will be restored to normal. Similarly, if the displacement is in the opposite direction, the screw 294, threaded through an outward extension from the slide, strikes against some such portion of the table as that holding the screw 293. The screw 294 may also be varied until it resets the upper section of the lever so that it is correctly related to the driving arm.

As the feed mechanism acts successively upon the lowest soles of the stack, those above it may become more and more disarranged, especially those adjacent to the foot 264 of the retaining rod. This tendency is corrected by a stack-rearranging or straightening member 295 fixed to a vertical shaft 296 arranged to oscillate in a depending portion of the wall-frame 210. The member 295 is shown as a skeleton-arm (Fig. 8) corresponding in height to the cut-away portion of the magazine-wall 204. Normally, this arm is held clear of the line of feed of the soles by a torsion-spring 297 surrounding the shaft and fixed at its ends to said shaft and to the lower bearing thereof. Attached to the bottom of the shaft is a pinion 298, with which meshes a segmental pinion 299 forming the upper arm of a lever having an extended fulcrum 300 turning beneath the table. The lower arm of the lever has a laterally projecting pin 301, which lies in the path of oscillation of the lever 271. After a sole has been advanced from the magazine and the feeding mechanism is making its return stroke, the lever 271, contacting with the pin 301, causes, through the gearing 299 and 298, the arm 295 to swing inwardly through the cut-away portion of the magazine, so that it contacts with the forward edges of a plurality of the lower soles of the stack, forcing these back, if they have been displaced, to a vertically aligned position in the magazine. There is shown interposed between the arm 295 and its shaft 296 a yieldable connection 303, this allowing the arm to be stopped after it has contacted with the soles, while the movement of the levers

271 and 300 continues. The lever 289, previously described as incidentally carrying the member 288, has its vertical end movable through an opening in the rear of the magazine into engagement with a plurality of the lower soles therein as they rest upon the elevating support 277. This lever 289 is normally held out of the magazine by a spring 302 (Fig. 10) which surrounds its fulcrum. At the beginning of each feed-cycle, a projection 303 upon the periphery of the cam-disk 274 comes into engagement with the lower extremity of the lever. This abruptly moves the upper end against the edges of the sole which is to be fed and those immediately above it, bringing them into vertical alignment, and producing a symmetrical relation of this portion of the stack in preparation for the feeding operation. The lever 289 will also insure the settling down of the lower soles upon the support 277, if they have failed to descend after the previous feeding operation.

To review the general operation of the sole-feeding mechanism and co-operating devices, it may be said that, at the beginning of the cycle, the lower portion of the stack, with its outer side elevated by the support 277, will have been trued vertically by the contact of the arm 295 under the influence of the returning feed-lever 271 and by the oppositely acting lever 289. As the feed-slides 268 and 281 approach their rearward positions, somewhat before the projection 279 has passed beyond the lowest sole, the contact member 284 is raised by the lever 285 as a result of the contact of the lever-pin with the end of the member 288. This elevation does not cause the immediate engagement of the member 284 with the soles, because the travel of the secondary slide 281 in this direction has been arrested near completion of the stroke of the lever 271 by the contact of 284 with the reduced extremity 280 of the gage-bar. At this time the spring 282 yields to permit the slide 268 to finish its outward movement, and there is produced between the contact members 278 and 284 a space sufficient to receive a sole. After the contact member 284 has been thus set, the remainder of the travel of the slide 281, before the member 284 strikes the gage-bar-end, is made possible by the depression of the pin 287 into a cut-away portion of the member 288. The upper wall of the cut-away portion resists upward movement of the pin and thus temporarily locks the member 284 in its active position. When the lever 271 begins its forward or feeding stroke, the projection 279 of the primary slide first contacts with the edge of the lowest sole, and, as the retaining member 284 is moved away from the gage-bar by the engagement of the opposite edge of the sole, the spring 282 holds said member in its engagement, so that the sole is

grasped and retained against angular displacement between the elements 278 and 284. These advance it below the gage-bar, which yields vertically to relieve any abnormal upward pressure due to distortion of the sole or the like, and carry it out upon the table 201, where it is to be released. This is accomplished by the engagement of the portion 290 of the retaining member by the spring 291, which depresses the member until it is below the plane of the sole, and the feeding mechanism is restored to its initial position by the opposite oscillation of the lever 271. This lever, if interference occurs to its movement in either direction, yields at the friction device 292, thus preventing injury to the directly associated parts, and is thereafter reset by the contact of either the screw 293 or 294.

By the mechanism just described, a sole has been placed upon the extension of the table 201 in approximately correct position for its transfer to a support 65. There remains to be accomplished its more exact adjustment. To effect this, there are provided opposite side contact members 304, 304 arranged to move through openings in the shelf 256 (Figs. 5 and 8). Said members 304 are preferably in the form of fingers pivoted upon levers 305, 305 fulcrumed at the upper ends of the arms of a yoke 306, which is fixed at the top of a vertical sleeve 307. The sleeve has a bearing for longitudinal movement in a bracket 308, this being resisted to the desired extent by an adjustable friction device 310, the purpose of which will appear shortly. Through the sleeve 307 passes a rod 312, the lower end of which carries a stud projecting into a slot in an arm 314 pivoted upon the standard 200. Upon the end of the arm is a roll 315 entering a cam-track 316 in the disk 274. Near the upper extremity of the rod 312, at its opposite sides, are formed racks 318, 318, which mesh, respectively, with gear-segments 320, 320 upon the levers 305, 305. The fingers 304, 304 are shown as drawn normally toward each other and also toward the table by a helical spring 322 joined at its extremities to the fingers, and resting at its side with some force against an upward extension 324 of the rod. This deflects the spring to one side of a straight line between the fingers, as is best shown in Figs. 13 and 14 of the drawings, tending to always urge them to the right, as viewed in these figures, as well as to move them toward each other. In their normal position, the upper ends of the fingers 304 are below the rear portion of the sole, which rests upon the shelf 256 with its cut-off end adjacent to a gage-wall 340, against separated contact-surfaces of which (Fig. 5) the straight edge of the sole is to be squared. Sole-engaging surfaces spaced in this manner are provided

to avoid errors in positioning which might be introduced by projections at the center of the cut-off sole-edge, these projections sometimes being formed in making the opening σ . The wall 340 is arranged to move across the shelf with the side wall 204 of the container, being mounted upon the slide 234, so that, in the adjustment of the magazine-walls for soles of different lengths, the gage-wall bears a fixed relation to those of the magazine. The gage-wall also has a predetermined angular relation to the longitudinal axis of the support 65, being preferably at right-angles thereto.

15 When the cam-track 316, in its travel, begins to act upon the rod 312, its first effect is to move the racks 318 upwardly past the gear-segments 320, the friction device 310 resisting the movement of the sleeve and yoke 20 which supports the fingers 304. The effect of this rack-and-gear connection is to separate the fingers, so that their adjacent edges may be farther apart than the maximum width of the sole to be operated upon. The 25 separation having been accomplished, the lower teeth of the segments strike upon the plane surfaces of the rod 312 below the racks. This compels the rod and yoke to move together, lifting the fingers until their upper 30 ends are above the sole. The cam-track 316 then reverses the travel of the rod 312, and in its descent there is an opposite action, by which the racks, first acting upon the segments while the sleeve and yoke are held stationary by the friction device, bring the curved and roughened grasping surfaces 328 upon the fingers into engagement with opposite edges of the sole, and then draw them down to effect a preliminary truing of its 35 longitudinal axis with respect to the axis of the support 65. While the fingers are still descending, cam-surfaces 330 upon their outer edges come into contact with a projection 332 upon the standard 201 (Figs. 13 and 40 14), rocking said fingers in the direction of the gage-wall 340. The engagement of the surfaces 328 with the sole forces the latter back against the wall, the fingers yielding against the spring 322, by virtue of their 45 pivotal connection to the levers 305, to permit this without interference. This action squares the straight rear edge of the sole against the gage-wall, and, by any necessary angular adjustment, completes the establishment 50 of a definite relation between the axes of the sole and support. At the same time, the opening σ in the sole is brought to a predetermined position. While the sole is still thus held by the fingers, it is engaged by 55 means for transferring it to the support which is at this time located at the operating mechanism of position A.

A device 344 for the transfer of the soles may be as more particularly disclosed in Letters 60 Patent of the United States No. 1,438,481,

dated December 12, 1922. Here it will be sufficient to say that it includes spurs 346, 346 (Fig. 12) entering and being locked in engagement with the sole upon downward pressure against the latter, and being released 70 when a controlling lever 348 contacts with a projection 350 (Fig. 7) upon the central standard 61. The transferring device is yieldably mounted upon the lower end of a vertical carrier-bar 352, its spindle 349 being pressed downwardly by a spring 351. This bar is pivotally supported upon arms 354, 354 carried by shafts 356, 356 journaled in a standard 357 mounted adjacent to the standard 200. Fixed upon these shafts are gear-segments 358, 358 meshing with a rack-bar 360 guided in casings 362, 362 supported upon the standard 357, and in brackets 364 also fixed upon the standard. To one of the shafts 356 a counterweight 365 may be attached to equalize the weight of the transferring device. A link 366 (Fig. 8) joins the bar 360 to the outer end of a lever 368 fulcrumed upon the standard 357. Articulated to the lever 368 is a connecting-rod 370 joined at its lower end to a crank 372 carried by the driven portion of the shaft 275. Initially, the device 344 occupies a position just above the table 201 at a point near the center of the sole placed thereon by the feed mechanism, as 95 hereinbefore described. As the crank 372 begins to rotate under the influence of the driving mechanism, the device 344 is first lowered, forcing the projections 346 into the sole. These are locked therein to hold it firmly in place, and, the fingers 304 having descended out of engagement with the sole and thus released it, the continued rotation of the crank reverses the movement of the transfer mechanism, causing it to swing upwardly and inwardly toward the turret until it assumes the position over a support 65, as 100 illustrated in dotted lines in Fig. 7. It should be noted, and this remark applies to other transferring mechanisms hereinafter described, that, during the entire transfer of the sole, it is maintained horizontal, as it was in its container, reducing the liability to accidental release, and that, moreover, the oscillation of the transferring mechanism in a vertical plane minimizes the space occupied circumferentially of the turret, and thus avoids interference between adjacent mechanisms. When the sole is in proximity to the surface 110 of the support, the release-lever 348 contacts with the tripping projection 350, freeing the sole-engaging projections and causing the sole to be deposited upon the support. When thus deposited, the pin 108 has been forced downwardly, this having been effectively accomplished by the vertical alinement of the transfer device 344 with the pin. The pin 66 has entered the opening σ in the sole, and the axes of the sole and support substantially coincide. 115

120

125

130

To facilitate the release of the sole from the projections 346 and to more certainly seat it about the support-pin 66, a displacing or pressure member 374 acts upon the heel-portion at the time of retraction of the projections. As appears in Figs. 13 and 14, this member extends from a head 375 fixed at the lower extremity of a spindle 376 guided for vertical movement in a sleeve depending from an arm 377 secured to the carrier-bar 352. The spindle, while restrained against rotation, is yieldable vertically against the expansive force of a spring 378, which surrounds the sleeve and spindle between the arm and head. The member 374 may be releasably held in a raised position, so that it is out of contact with the sole both upon the table and support, by a latch 379 pivoted upon the arm and arranged to engage the edge of the head adjacent to the displacing member. A spring 380, interposed between the arm and latch, aids in effecting the latching engagement, but the position of said latch is definitely governed by a link 381, which unites it to the lever 348 controlling the sole-engaging device. When this device is lowered into contact with a sole upon the table after having made a delivery to the support, the member 374 is unlatched and depressed by its spring, and before the spurs 346 penetrate the sole, its carrying head 375 strikes the top of the gage-wall 340. As the bar 352 descends, the latch 379 is carried below the head and engages it, thus retaining it temporarily set ready for action. The seizing of the holes by the spurs having been completed, the transfer device, with the latched-up displacing member 374, swings to a position over the support, and, as the lever 348 strikes and is turned in an anti-clockwise direction by the standard-projection 350, the link 381 draws the latch 379 away from the head 375. Consequently, just as the spurs 346 are retracted for the release of the transferred sole, the member 374 is forced down sharply by its spring 378, driving the sole over the pin 66, and at the same time aiding in freeing the former from the spurs.

As has been pointed out in connection with the description of one of the supports 65, the location of the roll 116, determined by the absence of a sole from the support or its presence thereon, governs the starting of the operating mechanisms. At position A, now under consideration, the sole-feeding mechanism and transferring mechanism must be set in action when a sole is lacking from the support. Under these conditions, the support-pin 108 is elevated, and the roll 116 drawn in, and here acts upon a device which produces engagement of the clutch 276 joining the sections of the actuating shaft 275 at this position. Of this clutch, the driving member is provided, as illustrated in Fig. 15 of the drawings, with a recess 382, near the

periphery of its inner face, this recess receiving a locking projection upon a dog in the form of a lever 383 centrally pivoted upon the driven section of the clutch. A spring-actuated plunger 384 tends to carry the end 70 of the dog or lever into the recess when this is brought into alignment with it, and also moves the opposite angular end 385 of the dog into a groove in a clutch-releasing member 386. When the portion 385 of the lever is 75 revolving through this groove, engagement of the clutch is established in the manner shown in Fig. 15. The member 386 is fixed upon the lower end of a vertical rod 387 (Fig. 16) mounted to reciprocate in brackets 388 80 upon the standard 357. Surrounding this rod is a spring 389 interposed between one of the brackets and a collar 390 secured upon the rod. The normal effect of the spring is to so elevate the releasing member 386 that 85 there is brought into co-operation with the end 385 of the dog a cam-surface 391 and a stop-wall 392 upon said member. Under these conditions, when the portion 385 reaches the cam-surface 391 in the rotation 90 of the clutch, the dog 383 is swung about its pivot to withdraw the opposite end from the recess 382. This having been effected, the portion 385 comes into contact with the wall 392, and the rotation of the driven section of 95 the shaft ceases. A sleeve 393 surrounds the upper end of the rod 387, there being interposed between the two a spring 394, the resistance to compression of which is less than that of the spring 389. The function of this 100 spring 394 will be stated later. Normally, the rod and sleeve move together as a unit, there being a latch 395 pivoted upon the collar 390 and lying beneath the end of the sleeve, being yieldably held in this position 105 by a spring 396 connecting the tail of the latch to the upper bracket 388. At the top of the sleeve is a head 397, lying in the circular path described by each roll 116 during the 110 rotation of the turret, and having at one end an inclined surface, up which this roll may ride and depress the sleeve and releasing member 386 against the spring 389. This 115 carries the stop-surface 392 away from the portion 385 of the dog, which swings into the space in the member 386, and when the recess 382 reaches the opposite extremity of the dog, the driving and driven members of the clutch are locked together to initiate the cycle of 120 operation of the feeding and transferring mechanisms at position A. This is repeated as long as there are a suitable number of soles in the magazine at position A, shank-pieces at position C and filler-pieces at position D, for although the roll 116 of one support may 125 leave the head 397 and allow the clutch-controlling rod 387 to rise, before the projection 385 has reached the cam-surface 391 the roll of the succeeding support will have depressed the head. The action of the mechanisms for 130

supplying soles to the turret-supports therefore normally goes on uninterrupted. When, however, a diminution of the supply of work-pieces, as will be described in detail in connection with positions A, C and D, causes the operation of controlling mechanism and the latch 395 is withdrawn from beneath the sleeve 393, the clutch-releasing member 386 is free to be raised by the spring 389 until the cam-surface 391 and stop-surface 392 are brought into the path of the dog-projection 385. As a result of this, the opposite end of the dog is cammed out of the clutch-depression 382, and the feeding and transferring actions are terminated.

It is, of course, important that, during the operation of the machine, there shall always be in the magazine a stock of soles, so that, for each engagement of the clutch mechanism under the control of the supporting roll 116, the feed of a sole and its transfer to the support will be effected. Were this not the case, the mechanism at position B would apply adhesive directly to the support, and this would be followed by the pressing of a shank-stiffener and a filler-piece upon the thus-coated work-supporting surface. To insure against the operator neglecting to keep a proper stock in the magazine, there is associated with it a stack-testing and clutch-controlling mechanism. Mounted to reciprocate horizontally in stationary guides at a suitable distance above the sole-support 277, say the height of four soles, is a contact-finger 398 (Figs. 10 and 11), surrounding which is a sleeve 399 engaging at its outer end a controlling arm 400 secured to the finger. Surrounding the rod and being under compression between the outer end of the sleeve 400 and a collar 401 upon the rod, is a spring 402. The finger is moved yieldably in to test the stack by engagement with a sleeve-lug 403, which straddles a horizontal projection 404 from the sole-feeding member 278, and receives the contact of a pin 405 extending through the projection, as the member 278 completes its feeding stroke. The return of the finger to its normal position is under the influence of an arm 406 depending from its outer end. The striking of the arm by the end of the projection 404 as the member 278 makes its idle stroke carries the finger to its initial position out of contact with the stack. If the soles in the magazine have fallen below the testing level, a screw 407, horizontally adjustable through the finger-arm 400, contacts with the head of a normally closed spring-actuated air-valve 408, of the plunger type. This valve, as may be traced in Fig. 29, governs a supply of air or other fluid under pressure admitted by pipes 409, 410 and 411. With the valve 408 open, this pressure is admitted to a cylinder 412 (Figs. 7 and 15) depressing a plunger 413 against the elevating action of a spring 414. By this

movement, an actuating arm 415, adjustably mounted upon the plunger by a bracket 416 (Fig. 16), is correspondingly lowered. The arm projects over a lateral extension from the tail of the latch 395, so that the downward travel of the plunger swings the latch away from below the end of the sleeve 393, releasing the rod 387. In spite of the fact that the roll 116 may now be above the head 397 of the clutch-controlling rod, holding the portion 386 in a position tending to maintain the engagement of the clutch, the force of the spring 389 is now sufficient to overcome the resistance offered by the spring 394, so that the rod rises independently of the sleeve-section 393, bringing the cam-surface 391 into the path of the dog-end 385. Therefore, the clutch members are separated in the manner which has just been described in connection with the termination of the normal feeding and transferring cycle. The operator, observing that the feed and transfer of soles have ceased, will be effectively warned that the supply in the magazine must be renewed. To render positive the effect of the air-impulse obtained by the momentary operation of the valve 408 in the testing reciprocation of the finger 398, a latch 417, pivoted upon a bracket 416 attached to the plunger 413, catches beneath a fixed guide for said plunger when the latter has been lowered. The clutch therefore remains locked out of engagement, regardless of the action of the air-pressure upon the plunger, until the latch has been manually released by the operator after he has filled the magazine.

*Operating position B—sole-cementing—
(Figures 17 to 25, inclusive)*

A sole having been placed upon the support at position A, the driving mechanism acts at the end of the predetermined operating period, under the control of the Geneva stop mechanism, to rotate the turret and the work-supports, the one under consideration passing to and coming to rest at position B. Into co-operation with the mechanism at position A an empty support is brought, while at the companion operating positions other actions are taking place, each of which will be described in the order in which they occur. At position B, outside the path of the supports 65, rises from the base a standard 420. Between this and a ring 421, clamped upon the turret-standard 61, extend spaced rods 422, 423 (Figs. 1 and 17) furnishing a track or ways upon which is arranged to travel a carriage 424. Mounted upon this carriage is a pot or receptacle 428 for the cement which is to be employed. For the present work, certain asphaltic preparations such as are employed for roofing form suitable adhesives. At the inner portion of the receptacle is an extension 430, in the bottom of which is a passage leading to a nozzle 432 (Fig. 19) having a

vertical discharge-opening, which is preferably formed in a renewable bushing 434. The separable nozzle facilitates repair and change for producing different rates of flow. The cement may be maintained in proper condition for delivery through the nozzle by a heating device, consisting in the present instance of electric units 433 contained in a vertical opening through a boss projecting at the inner side of the casing-extension 430, and through openings in similarly thickened portions of the receptacle-walls. The units are supplied with current by conductors 435 from any convenient source. Co-operating with the opening in the bushing or nozzle 434 is a valve 436, the enlarged body 438 of which is guided in the upward extension of the nozzle, which enters the casing. This body-portion is grooved within the passage through the nozzle to permit the flow of cement past it to the opening under the control of the valve 436. Rising from the valve-body is a stem 440, having at its top a fitting 442 guided within a yoke 444 secured at the top of the casing. A screw 446, threaded vertically through the yoke, serves as an abutment for a spring 448, which is interposed between this screw, or a plate resting against its end, and the top of the fitting 442. Change in the position of this screw permits the resistance of the spring to be varied, and consequently the proper force applied to hold the valve 432 against its seat in the nozzle. The fitting has an arm 450, which has, adjustable as to position in it, a vertical contact-rod 452, which may be guided and held against lateral movement by a bracket 453 extending from the side of the yoke member.

Upon the carriage 424, below the rod 452, is fixed a bracket 454, in which is guided for vertical reciprocation a slide 456 having journaled upon it two rolls 458 and 460. The roll 458 travels in the reciprocation of the carriage in such a horizontal plane that it strikes a cam-surface 462 at the end of a horizontal rod 464 clamped adjustably by a set-screw 466 in a socket 468 carried by the ring 421. The slide 456 is raised by this engagement of the roll with the cam-surface, and with it a plunger or slide-section 470 movable in a socket in said slide alined with the rod 452. This plunger is backed by a spring 471, which is located in the socket, and offers such resistance to compression that, in the normal operation of the cementing mechanism, it does not yield. The upward movement of the plunger, under the influence of this spring, is limited by a pin 472 forced against the upper extremity of a vertical slot in the slide. When the cement in the receptacle is in proper fluid condition, the elevation of the slide by the cam-surface 462, without affecting the spring 471, moves the head of the plunger until it strikes the lower extremity of the rod 452. This raises the fitting 442 and compresses the

spring 448, which is lighter than the spring 471. The valve 436 is thereby drawn away from the nozzle-opening, producing a flow of cement, which gathers in a spot of considerable area, as indicated at *a* in Fig. 18 of the drawings. A comparatively extensive coating of the adhesive is desirable at this point, because of the tendency of the forepart of the filler-piece *f* to separate from the sole. At this time, the travel of the carriage 424 is 75 reversed, so that the roll 458 leaves the cam-surface, and the valve is closed by the spring 448, stopping the flow of cement. If, because the machine has been idle and current cut off from the heating units, the cement in the receptacle is cold, the valve may tend to stick upon its seat, and if the lifting force of the cam-surface 462 were allowed to be exerted unmodified, breakage of parts might result. The spring 471 guards against this, since, 80 under some pressure greater than normal but less than that which would be harmful, it yields, so that the slide 456 may be lifted by the cam-surface, the slot in which the pin 472 lies permitting this movement to the full extent produced by the cam. The valve may therefore remain fixed upon its seat until the condition is removed by the operator.

In addition to the coating *a* of cement at the forepart of the sole, it is desired to deposit strips at *b* and *c* to cause the adhesion of the shank-piece *s*, and also a certain area of the filler-piece outside the shank-piece. Furthermore, it is preferable to have an uncoated space between the strips *b* and *c*, into 95 which the transferring device of the shank-piece position *C* may descend without becoming smeared with the adhesive. For the accomplishment of this purpose, while the carriage is moving outwardly after the spot *a* 105 has been coated, the slide 454 is elevated through the second roll 460, rotatable between walls bearing cam-surfaces 474 (Figs. 20, 21 and 22), against which journals 475 of the roll act. At the ends of the cam-surfaces are 110 stop-walls 476, 476, which retain the roll journals in co-operation with the cams. The roll 460 runs in constant engagement with the upper surface of the rod 423, successively entering cam-depressions 477, 478 and 479 therein, 115 this order of engagement being for the inward travel of the receptacle first mentioned. The roll 460, which is initially resting in the depression 477, first, as a result of the consequent lowering of the slide 456, holds the 120 valve 434 closed, so that no cement is delivered. As travel to the left, as viewed in Fig. 17 of the drawings, begins, the roll, upon encountering the end of the depression 477, is held back, so that its journals come beneath 125 the high portion of the cam-surfaces 474. When said roll rides from the depression upon the elevated surface of the rod 423, the extent of resulting upward movement of the 130 slide is not sufficient to bring the plunger 470

against the rod 452 to open the valve. This action is well shown in Figs. 20 and 21, the elevated position of the slide being indicated in dotted lines in the second of these figures. The same action takes place at the succeeding depressions 478 and 479. After the opening of the valve by the cam-surface 462, as has already been described, the carriage 424 returns to its initial position. At this time, with the roll 460 traveling to the right (Fig. 22), the engagement of the roll-journals with the right-hand end of the depression 479 holds the roll back and through the cam-surfaces 474 exerts a lifting effect until the low ends at the rear walls 476 reach the journals. Consequently, the slide 456 is raised before the roll leaves the depression, and, when the higher level at the upper surface of the rod 423 is attained, the slide has been elevated to a sufficient extent to open the valve, this being as shown in dotted lines in Fig. 22. Therefore, during the advance of the roll from the depression 479 to 478, cement is being laid along the strip *b*. While the roll is in the depression 478, the valve is again closed and an uncoated area results. Then, when the roll reaches the depression 478, the action at 479 is repeated. The valve is again opened and the flow of cement begins, to be again terminated by the closing of the valve at the depression 477. The strip of cement *c* is thus laid, and the coating operation is terminated just before the thus-coated sole is carried to the next position. The time during which the cement may harden before the other work-pieces are applied to the sole is therefore reduced to a minimum.

The shank-pieces vary in length to correspond to the sizes of soles operated upon. To maintain a constant relation of the outer end of the adhesive-strip *c* to the opening *o* and the adjacent straight edge of the sole, the location of these sole-portions upon the support being determined by the position of the pin 66, the action of the roll 460 upon the cement-valve is governed in the adjustment of the walls 204 and 206 of the sole-magazine and other associated elements, which include the support-pin. For this purpose, as is most completely represented in Fig. 53, the adjusting spindle 228 for the walls of the magazine 199 is joined by spiral-gearing 480 to a shaft 481 journaled upon an extension from the slide 224 (Fig. 8). This shaft is united through bevel-gearing 482 to a shaft 483 formed in telescopic sections, the outer one of which is journaled in the element carrying the shaft 481, while the other is rotatable upon the table 201 (Fig. 1). At the extremity opposite the gearing 482, the shaft 483 is connected by a universal joint 484 to a shaft 485 having a universal joint 486 between it and a shaft 487 journaled in a bracket 488 fixed to the standard 61 at position E (Fig. 44). A train of connections,

consisting of bevel-gearing 489, a shaft 490 mounted to turn in the bracket 488 and ring 421, and bevel-gearing 491, continues the transmission of movement originated at the hand-wheel 232 on the spindle 228 from the shaft 487 to a shaft 492 journaled upon the ring 421 at position B (Fig. 17). The shaft 492 is threaded at its outer end into a lug 493 secured to the cam-rod 423, which is arranged to slide in the standard 420 and in the ring 421. Rotation of the hand-wheel 232 is communicated to the shaft 492, causing the threaded connection to move the rod 423 longitudinally in its guides. By correctly proportioning the connecting train, the point at which the outer end of the strip *c* of cement is terminated by the depression 477 may be caused to lie at the same distance from the sole-opening *o* for all sizes of soles, and this without other consideration on the part of the operator than the setting of the index point at the appropriate scale division 236 corresponding to the size of sole to be operated upon.

The carriage 424, with the receptacle 428, is reciprocated to move the nozzle over the work by a link 494 articulated to the carriage and to a lever 495 fulcrumed upon the standard 420. Like the lever 271 at position A, the lever 495 is sectional, with the sections united by a friction device. Therefore, if the receptacle 428 offers excessive resistance to movement, the slipping of the friction will allow the upper section to remain stationary, while the actuating oscillation of the lower section continues. The normal relation of the lever-sections may be restored by contact of the ends of the carriage 424 with the guide-portions of the ring 421 and with the standard 420, respectively. The lower extremity of the lever 495 is joined to an eccentric-rod 496 pivoted upon the strap of an eccentric 497 loosely mounted upon the shaft 154. Fulcrumed upon the hub of the eccentric is a lever 498, the inner end of which is turned down and forced by a spring 499, interposed between the opposite arm of the lever and a projection from the eccentric-hub, toward a circular series of depressions 500 in the upper surface of the gear 157 (Fig. 23). The lever is normally held disengaged from the gear-depressions by contact with it of a plunger 501 drawn by a spring 502 into the path of the lever when it revolves. Formed upon the upper extremity of the plunger is an inclined surface 503, so related to the path of the roll 116 of the support, when said roll is in its outward position as a result of the presence of a sole upon the support, that these elements will contact in the revolution of the roll. The latter rides under the surface 503, thus raising the plunger to free the lever 498. The downturned end thereupon enters one of the depressions in the gear 157, which is constantly rotating,

thus transmitting this rotation to the eccentric, which acts to oscillate the lever 495 and thereby reciprocate the receptacle, carrying the nozzle over the work. As the receptacle 5 advances, the valve 434 is opened, first, at the termination of the inward travel of the receptacle by the cam-surface 462, to produce the spot *a* of cement upon the sole, and then, upon the return travel by the surface of the rod 423 between the depressions 479 and 478 and between 478 and 477, to cause, respectively, the laying of the strips *b* and *c*.

Operating position C—shank-piece-applying mechanism—(Figures 26, 28 and 30 to 35, inclusive)

Following the cementing operation, the support upon which the sole, the assembling of which is being traced, is mounted, is revolved to and stopped at position C. Here, upon a standard 510 is a container 511 for shank-pieces *s* (Fig. 30), which may consist of stampings of sheet-steel or other material of the desired form, each having near one extremity an opening *p* which is adapted to receive the support-pin 66 when the shank-piece is placed upon the compound sole being assembled. This container is carried upon the yoke-shaped end of a bracket or holder 512 fixed to an arm 514 projecting from the side of an upward extension 533 of the standard 510. Said container may be in the form of a magazine arranged to contain a stack of shank-pieces, and having end walls 516, 516 (Fig. 28) with horizontal projections 518, upon which the extremities of the contained objects rest when the magazine is removed from the machine. One side of the magazine is shown as closed by a wall 520 secured to the end walls and unbroken, save for a space 521 at the bottom, through which the shank-pieces may be removed laterally one by one, while opposite this the end walls bear flanges or narrow side walls 522, 522. To correctly locate the contents, the dimensions of the magazine in horizontal section are substantially the same as the maximum longitudinal and transverse dimensions of the shank-pieces which are to be received. As these shank-pieces correspond in size to the soles to which they are to be applied, a plurality or set of magazines is employed, one for each size. They are located upon the bracket 512 by pins 524, 526 projecting from the lower portion of the walls 516 and resting in slots or sockets 528 (Fig. 30) in the upper edges of side flanges of the bracket. The pin 524 permits the end wall, against which are placed the ends of the shank-pieces containing the openings *p*, to be arranged in a constant relation to a fixed point of reference, which will again be more definitely mentioned. The pin 526 varies in length inversely as the length of the magazine and contained shank-pieces. For the largest size of shank-piece, the walls

516, 516 are in substantial contact with the bracket-flanges, and thus determine the relation of the inner ends to the reference point. For the smaller sizes, each pin 526 has an enlargement 530 extending just far enough 70 from the wall 516 to fill the space between it and the bracket-flange, in which said pin is supported. Thus, the constancy of relation of the opposite or inner end of each magazine is maintained. Each magazine is held 75 against tilting in the bracket by the engagement of its wall 520 with a vertically extended surface 525 between the flanges in which are the slots 528. To most advantageously locate the upper edge of an opening in the bracket-wall 525, with which is alined the magazine-opening 521, so that it will release the lowest shank-piece, while retaining those above against displacement, this retaining portion of the wall may be in the form of a gate furnished by the ends of bars 527, 527 guided in slots in the wall 525 and adjustable as to height by screws 529. The separately movable bars may be so located as to cause the curved shank-pieces to be most accurately 80 delivered.

To feed the shank-pieces successively through the magazine-opening 521 and beneath the bars 527, 527, there is journaled in the standard 510, and in the arm 514, a shaft 534 having fast upon its upper extremity a delivering disk 536. The axis of this shaft furnishes the reference point previously mentioned, with respect to which all sizes of shank-pieces are definitely located. Upon its upper face, the disk is provided with two concentric raised portions or ribs 538, 538 (Figs. 30, 31 and 32), so placed as to lie at opposite sides of the centers or points of greatest curvature of the shank-pieces in the magazine. The ribs are preferably formed in segmental blocks 541 secured to the face of the disk, and spaced from one another at the ends. The height of the ribs 538 is such that, when the lowest shank of the stack rests upon them, its ends are clear of the magazine-projections 518, the weight of the stack being carried entirely upon the ribs. This permits the lowest shank-piece, under the influence of the weight of the superposed pieces, to enter some one of a plurality of slots 540, here shown as five in number, formed radially of the disk across the ribs at the ends of the blocks 541. The slots are caused to travel 100 by rotation of the shaft 534 into alinement with the magazine to receive a shank-piece. At the time of such reception, a previously removed shank-piece, resting in another slot, is being transferred to the support 65. The shaft 534 is driven through spur-gearing 544 and worm-gearing 545 from a sectional main shaft 542 (Fig. 26) journaled in bearings upon the standards 61 and 533 at position C. The driven and driving gears of this pair 105 544 have, respectively, unbroken or toothless 110 545.

convex and concave portions 546, which, when in engagement, stop the rotation of the shaft 534, and therefore of the delivery-disk, interposing definite periods of rest between the periods of rotation when the teeth of the gears 544 are in contact. These intermittencies of rotation of the disk give time for the removal of the shank-pieces from the disk-slots. Included between the sections of the shaft 542 is a clutch mechanism 547, which may be similar to that at position A, but is actuated by an unbroken rod 548 to cause the sections of the main shaft to turn together through a single rotation when it is lowered from the position to which it is normally raised by a spring 549. This rod-depression is the result of contact of the support-roll 116, which is here held outwardly, as it was at position B, by the contact of the sole carried with the support-pin 108. The driven element of the clutch receives rotation through the bevel-gearing 163 from a vertical shaft 552, which is driven by the sprocket-gearing 162, as has already been described in connection with the general actuating mechanism of the machine. A crank 554 is formed upon the driven portion of the shaft 542, and reciprocates, by means of a connecting-rod 556, lever 558 and link 560, a vertical rack-bar 562. The weight of the bar may be at least partly counteracted during a portion of the travel by a spring 564 situated between it and a supporting projection from the standard 510. This relieves a tendency of the transferring elements to produce movement by their weight at certain times during the disengagement of the clutch 547. This bar is guided in a like manner to that at position A, and meshes with corresponding gear-segments 566 turning with shafts 568 journaled in the standard-extension 533. Fixed upon the shafts 568 are arms 570, to which is pivoted a bar 571 normally extending vertically above the stopping place of one of the disk-slots containing a shank-piece. Carried upon the lower extremity of the bar 571 is a shank-piece-picking or transferring device 572. This device may be substantially as set forth in Patent No. 1,438,480, dated December 12, 1922, it including a pair of yieldable jaws 573, which are separated to seize and release the pieces by pressure directly upon them, though any other suitable arrangement may be employed. From the initial position, shown in full lines in Fig. 26 of the drawings, the device 572 is first lowered under the influence of the crank 554 to grasp a shank-piece which has been brought from the magazine by one of the slots 540, and is then carried upwardly and inwardly to the position appearing in dotted lines in the same figure, releasing the shank-piece held when this comes in contact with the sole upon the alined support 65 at position C. The crank mechanism then returns

the picker over the delivering disk. In thus seizing the shank-pieces, the jaws 573 of the transfer device enter openings 574 at the ends of the blocks 541 substantially midway between the ribs 538. To hold the shank-pieces against movement in the slots 540, so their constancy of relation to the axis of the disk shall be maintained, and therefore to the point at which they are seized by the transferring device, magnetic retaining means is provided. The blocks 541 are constructed of some such metal as steel, and are magnetized so that the adjacent ends of the blocks are of opposite polarity. The disk is of non-magnetic material, as brass. Because of this arrangement, there is produced between the ends of the blocks and traversing the steel shank-pieces contained in the slots, a magnetic field, which retains said shank-pieces constantly against displacement from the time they enter the slots until the positive lifting force of the transferring device 572 is applied to them.

When the delivering disk takes from the magazine a shank-piece in a slot 540, there should be no projecting edges parallel to the length of the piece, against which it may catch and thus be prevented from seating itself in the slot. The presence of such projections is guarded against at the spaced ends of the blocks 541 by making each oppositely inclined toward the center between the ribs 538 with the adjacent surfaces parallel to each other, as appears at 575 (Figs. 30, 31 and 32). With this arrangement, the V-shaped dividing space between the blocks is gradually presented to a shank-piece received in the slot, there being always a supporting surface at each side of the block beneath the down-tilted edge of the piece until it is fully deposited in the slot.

A shank-piece might be missed by the transferring device and left on the tops of the ribs of the delivering disk, instead of seated in a slot. As the piece thus out of place is carried forward by the disk, it may reach the magazine at the side opposite the delivery-opening 521 and clog or otherwise interfere with the rotation. This is made impossible by an inclined ejecting member 576 (Fig. 30) mounted upon the arm 514 and overhanging the disk between the point of action of the transferring device and the magazine, in the direction of advance of the slot. It not only conforms to the upper surfaces of the blocks 541 and the adjacent outer portion of the disk over its entire lower edge, but at its inner extremity has a reduced portion 577 lying in a groove in the inner rib. This insures the improperly supported shank-pieces brought against it being deflected upon its surface, which slopes downwardly and outwardly. The thus-displaced shank-pieces slide down the incline, and are dis-

charged from the machine clear of the disk and other moving elements.

As the transferring mechanism has thus far been described, it is so organized that the device 572 will grasp a shank-piece in a predetermined relation to its opening p and elevate it for delivery to the support 65 and for the entrance of the pin 66 into said opening. Since, however, this pin is differently positioned for each size of sole operated upon, it is necessary to similarly adjust the transferring device. This is preferably accomplished during the transferring operation by an automatic shifting of the device 572 to an extent determined by the setting of the slide 224 at the sole-magazine at position A, which, it will be remembered, provided for the adjustment of the pin 66 together with the setting of the magazine walls. To thus govern the shank-transferring device, it is preferably mounted to slide in horizontal ways 578 (Fig. 26) carried at the lower extremity of the bar 571, being kept in the position to which it is moved by the frictional resistance of the ways. The sliding portion of the device has, at its opposite ends, rolls 579 and 580, respectively. The function of the roll 579 is merely to so position the transferring device by contact with a fixed abutment-bar 582, mounted upon an arm 584 secured to the extension 533, that it will have a predetermined relation to the axis of the delivering disk. It will therefore correctly engage a presented shank-piece upon the disk, and will initially convey this above the support 65 to a position at least as far inwardly over the support as is required for the shortest size of sole. To this preliminary setting, a correction is then applied in the following manner: Upon an arm 586 secured to the standard 61 is arranged for horizontal adjustment, by a bolt-and-slot connection 588, a carrier-frame 590, in which are guided the supporting rods 592, 592 of a vertical contact-bar 594. Pivoted upon the carrier-frame is a gear-segment 596 meshing with an idler pinion 598 turning upon the frame and, in turn, engaging a rack 600 formed upon the under side of the upper guide-rod 592. A spring 602, interposed between the outer end of this guide-rod and the carrier-frame, acts upon the gearing to take up lost motion. The segment is connected by a link 604, having universal joints 606 at its engaging ends (Fig. 53), with a sliding locating device 608 for simultaneously positioning the transferring mechanism at position E, as will be particularly described in connection with said position. This device 608 is mounted upon bracket 488 (Fig. 44) secured to the standard 61, and receives motion from the shaft 487 through bevel-gearing 610 and a threaded shaft 612 rotated thereby. Shaft 487, it is to be noted, is included in the connecting train between the hand-wheel 232 at position A and the valve-controlling bar 423 at position B. Upon rotation of the hand-wheel, the effect of the connections just traced is to move the bar 594 to correspond to the location of the support-pin 66, as determined by the size of the sole operated upon. Now, as the transferring device 572 descends, its roll 580 encounters the bar 594. This moves the transferring device in its ways until the opening p in the shank-piece which is grasped is brought into vertical alignment with the support-pin 66. Consequently, as the delivering movement of the transferring device is completed, the opening encircles the pin, and the shank-piece is laid in the correct relation upon the coated sole. Upon the return of the transferring device to the magazine, it maintains its just-determined position in the ways until the roll 579 strikes the bar 582. This restores the device to its normal relation, ready for engagement of another shank-piece and control by any setting which the bar 594 may have during the next transfer. Similarly to the conditions at the sole-magazine, the operator should be warned when the lowering of the stack of shank-pieces renders it desirable. Means is provided for this, and since a shank-piece should not be withheld from a sole already applied to the support 65 at position A, the operator is informed of the need of a fresh supply of shank-pieces by a stopping of the feed and transfer of the soles, while the delivery of said shank-pieces temporarily continues. Arranged to oscillate about a spindle 614 (Figs. 30 and 31) secured at the outer portion of the frame-arm 514 is a lever 616 having mounted to turn upon it a roll 618 held against the periphery of disk 536 by a spring 620 extending between the lever and arm 514. The lever has an arm 622, provided at its outer end with a stack-testing finger 624 situated opposite the open side of the magazine at a distance from the bottom which will leave at least a certain limited supply after the stack has lowered to the test-point. This test is made once during each rotation of the disk 536, the finger being permitted to enter the magazine as a result of the cooperation with the roll with a depression 626 in the disk. If at this time the finger contacts with shank-pieces in the magazine, it exercises no controlling effect; but if it continues its inward movement to the extent allowed by the depression, the outer end of a slot in the lever engages a pin 628 depending from a connecting-rod 630. The opposite end of the rod is joined to an arm 632 fast upon a vertical spindle 634 (Fig. 26) journaled in the arm 614 and at the top of the standard-extension 533. A spring 636, encircling the spindle, holds the arm 632 yieldably against a fixed stop-pin 638. While the roll 618 rests upon the unbroken edge of the disk, the con-

necting-rod pin 628 is at the outer extremity of the slot in the lever 616. When the roll enters the depression 626, the spring 620 swings the lever so that the outer end of the slot presses against the pin, but is stopped by the engagement of the finger 624 with shank-pieces in the magazine if there is a sufficient number. If they have fallen below the level of the finger, it travels farther in to the magazine, and the end of the slot, by its pressure upon the pin 628, turns the spindle 634 against the resistance of the spring 636. Fixed upon the top of the spindle is an arm 640 (Fig. 29), which is carried in the rotation of the spindle against the stem of a plunger-valve 642 held normally closed, similarly to valve 408 at position A. This valve 642 governs the admission of air-pressure from the pipe 409 through pipes 644 to the cylinder 412 at position A, the associated elements of which disconnect the clutch 276, stopping the sole-feeding and transferring mechanisms. The machine, however, will continue to deliver shank-pieces to complete the soles which are already upon the supports at positions A and B, while the operator will be warned by the ceasing of the sole-supply that he must fill the shank-piece magazine.

With a suitable transferring mechanism such as that herein disclosed, it is reasonably certain, if a shank-piece has been delivered from its magazine, grasped by the jaws 573 and started upon its travel toward the support 65 which is stopped at position C, that it will be properly delivered to the coated sole upon said support. To avoid the possibility of a sole going through the machine and being finally delivered without its shank-piece, due to a failure to feed this from its magazine or to initiate the transferring action, the apparatus is so organized that, if the transferring device makes its delivering oscillation without a shank, a clutch 645 (Fig. 36), through which is driven the filler-piece-feeding mechanism at position D, will be disconnected. As a result of this, no filler-piece will be laid unless a shank-piece is in place, and the delivery from the machine of a sole having a concealed defect will be prevented. The operator's attention is, of course, also directed to the trouble. Mounted to slide vertically in guides 646 upon the transferring device is a testing or contact member 648 (Fig. 33). This is shown as maintained by gravity in a normally depressed position, with its lower end extending into the plane in which a shank-piece is held grasped between the jaws 573. The upper end of the contact member has, resting upon it, an actuating member 650 pivoted upon the transferring device. Upon the proper engagement of a shank-piece by the jaws, this presses against the member 648, raising its upper end, and with it, the actuating member 650. In this position, this member 650 travels in the

shank-piece-delivering movement of the transferring device above a pivoted contact-portion 652 (Fig. 35) held outwardly by a spring-pressed plunger 654 from the end of an arm 655. This arm is fast upon the upper extremity of a spindle 656 (Fig. 26) mounted to turn in a vertical position upon the extension 533. If the transferring device 572 has failed to grasp a shank-piece, then the members 648 and 650 are both lowered. This position of the last-mentioned member is indicated in dotted lines in Fig. 33 of the drawings. When thus disposed, instead of passing clear of the contact-portion 652, it strikes it in a direction opposite to that which would cause the recession of the plunger 654. This rotates the spindle 656, and with it an arm 657 secured upon the spindle at its lower extremity. A connecting-rod 658, guided at 659 upon a bracket 660 carried by the frame at position D and normally urged to the left (Fig. 35) by a spring 661 (Fig. 26) surrounding the spindle 656, has a pin 662 depending from it. The just-described rotation of the spindle moves the rod 658 and this pin 662 to the right, and this is communicated to a pin 664 (Fig. 34) projecting horizontally from a latch 666 pivoted upon a bracket 668 fast upon a rod 670 governing the clutch 645 at position D. This rod is sectional and spring-actuated, its effect upon the clutch 645 being in every essential particular the same as that of the rod 387 at position A, except that the operation governed by the clutch at position D is more rapidly performed. Therefore, no detailed description of these devices or their manner of operation will be here given. At the bottom of the latch 666 are oppositely inclined surfaces 672 and 674, with either of which may contact a spring-pressed plunger 676 guided in a depending portion of the bracket 668. When the surface 672 is engaged by the plunger, the latch is held in toward the rod 670 to maintain its sections against relative movement, and the arrival of one of the rolls 116 over an extended head 678 of the rod starts the filler-feeding mechanism by the lowering of said rod and the consequent engagement of the clutch 645. This action is repeated for each support. If, however, as was above described, there is no shank-piece engaged by the transferring device, and as a result of this the connecting-rod has moved its pin 662 against the latch-pin 664, the latch is carried away from the rod 670, leaving its sections free for independent movement. As the machine is organized, the roll 116 has at this time passed just beyond the head 678 of the rod, which has been raised by its lower spring, thus disconnecting the clutch 645 and stopping the delivery of filler-pieces at position D. The latch is held disengaged from the clutch-controlling rod by the pressure of the plunger 676 against the latch-surface 674, and when

the roll of the succeeding support reaches the head 678, the upper spring yields, the lower section of the rod 670 remaining unaffected and the clutch disengaged. As the upper section of the rod is thus idly depressed by the passing roll, an inclined surface 680 upon the latch is struck by a roll 682 rotatable upon a bracket 683 fixed to the descending section. The latch is thus swung in, so the plunger 676 rests against the latch-surface 672 and forces the upper end of said latch toward the rod. Finally, when the roll leaves the head 678 in the rotation of the turret, the upper section of the rod is elevated by its spring, 10 and the latch again assumes its inmost position, as illustrated in Fig. 34 of the drawings, holding the rod-sections in their normal relation. After the release of the arm 655 by the inwardly moving member 650, the spring 661 15 carries the rod 658 to the left (Fig. 35), so that it and the connected elements assume their initial positions. During the return travel of the transferring device, there is never a shank-piece between the jaws 574, 20 so the member 650 is always, during this period, in position to engage the arm-portion 652. Upon pressure against the portion in this direction, the plunger 654 yields, so that there is no interference between the elements. 25 If, upon the next action of the device 572, a shank-piece is transferred, it will find position D ready for action, because of the resetting of the latch 666 to cause the engagement of the clutch 645; but if the absence of 30 a piece from the jaws 573 causes the elements 650 and 652 to contact, the latch will be again withdrawn from the rod 670 and filler-piece delivery will not be effected.

40 Operating position D—filler-applying and work-pressing mechanisms—(Figures 27 and 36 to 43, inclusive)

Rotation of the turret now brings the support 65 to position D, at which there is to be applied, over the shank piece held upon the cemented sole, a filler-piece, which will later occupy the space within the edges of an upper, when this and the sole are brought into association. This filler-piece may be of a 45 plurality of layers of some such absorbent material as paper impregnated with asphaltum, or other substance which is more or less solid under normal temperatures of the air, but may be made plastic by the application of heat. Its form may be as illustrated at *f* in Fig. 40, it having a depression *q* adapted to receive a support-pin 66. These filler-pieces are carried in a stack at the top of a 50 standard 700 (Fig. 36) rising from the base 55 opposite the support at position D and furnishing a table. They are shown as held in a magazine or container 702, with the toe-ends in a constant relation longitudinally of the axes for all sizes. Here they engage a 60 V-shaped wall 704, the lower end of which

is sufficiently raised above the supporting surface for the stack to allow the free passage beneath it of the lowest filler-piece, those above it being retained against movement by the wall. This wall is fixed to a frame 706 70 arranged to slide transversely of the axes of the filler-pieces upon a cross-bar 708, supported by a pair of uprights 710 rising from the top of the standard. The opposite extremity of the magazine is furnished by a vertical bar 712, which is so formed at its inner edge as to generally conform to the depressions *q* in the filler-pieces. The bar is shown as supported upon a column 714, the lower portion of which is forked and guided in ways in upward projections 716 from the standard (Fig. 41) to slide longitudinally of the filler-piece axes. A weight 717 may be placed upon the top of the stack of filler-pieces to insure their downward movement in the magazine after a feeding operation (Fig. 37).

The filler-pieces vary in length in proportion to the sole-sizes, and, to correctly locate the magazine-bar 712 for each length, its supporting column is joined to the adjusting train which receives its motion from the hand-wheel 232 at position A. This may be accomplished by a shaft 718 (Figs. 40 and 53) united by universal joints 720, 720 at one end to the shaft 487 at position E, and at the other end to a shaft 722 journaled horizontally upon the top of the standard 700, and having a screw 724 meshing with a nut 726 mounted upon the column 714. When the operator, under the guidance of the graduations 236, makes settings of the elements at positions A, B and C, as has already been described, and those of the elements at position E and for determining the location of the support-pin 66, as will be more particularly brought out later, the rotation of the screw 724 moves the bar 712 to proportionate extent. Without other effort on the part of the operator, this alters the longitudinal dimension of the magazine for co-operation with the particular size of sole, and therefore of filler-piece, which is to be operated upon.

Because the foreparts of right and left shoes swing oppositely with respect to their longitudinal axes, it is necessary to take into consideration to which of these belongs the filler-piece and sole being operated upon, to attain the assembling of these in symmetrical relation. The initial positioning of the filler-pieces in this connection is obtained in the magazine by moving, to one or another of two opposite extremes and transversely of the longitudinal axes of the pieces, the sliding frame 706 carrying the toe-retaining wall 704. Co-operating with the slide is a stop-pin 730 projecting from the bar 708, the contact with this pin of opposed walls 732, 732 upon the slide so limiting its travel that when one or the other of the walls engages the pin, 130

the magazine is prepared to receive either a right or a left filler-piece. In either case, the slide is temporarily held in the desired position by a latch 734 pivoted upon it and capable of being raised above the pin to allow shifting the slide, or lowered so that one of its edges bears against the pin at the side opposite the slide-wall to retain the adjustment of the magazine for right or left filler-pieces. In making the adjustment, the operator lifts the latch and moves the slide until its wall gives the desired setting contact with the pin, then allows the latch to drop to secure the slide in place.

Beneath the magazine, extending longitudinally of the filler-pieces, is an opening, at the sides of which are ways to receive a reciprocating delivering plate 735, which has two surfaces, at different elevations, to support the stack of filler-pieces in the magazine (Fig. 36). The lower of these surfaces, designated by the numeral 736, holds the bottom piece of the stack at the proper level to be fed beneath the wall 704 in the reciprocation of the plate, while the upper surface 737 supports the remainder of the stack during this feeding action. The plate 735 is reciprocated by engagement with a rack 738, depending from its under side, of a gear 740 rotatable within the standard 700. Mounted to turn with the gear is a pinion 742 meshing with a segmental gear 744 also journaled in the interior of the standard. This segmental gear engages a rack-bar 746 guided for vertical movement within the standard. A connecting-rod 748 unites this bar to a crank 750 upon the driven portion of a sectional shaft 752, rotatable in bearings upon the standards 61 and 700. The driving portion of the shaft 752 receives power from position A by way of sprocket-gearing 164 and 166, a vertical shaft 754 and the bevel-gearing 167. The clutch mechanism 645 is interposed between the sections of the shaft 752, as has already been described in connection with its control because of failure to transfer a shank-piece at position C. In its normal action, the head 678 of the rod 670 is depressed by a support-roll 116 to cause the engagement of the clutch and the operation of the mechanism at position D, just as the like elements function at position C. For each revolution of the crank 750, the plate 735 is moved forward from beneath the magazine 702, carrying with it, over the support 65, the lowest filler-piece which lies over the surface 736, ready for action upon it of the mechanism to be described. In this travel, an inclined surface 760, between the stack-supporting surfaces 736 and 737, engages the filler-piece in the stack which is above that being delivered, and elevates this slightly to guide the surface 737 into its stack-supporting relation without a tendency to displace the filler-pieces. The feeding action of the plate 735

is relatively rapid, to leave the maximum time for the application of pressure to the work upon the support which is to follow.

To hold, during the feeding operation, the correct angular relation of the filler-pieces, which has been set up in the magazine, and to provide the desired varying points of feeding engagement with the depressions *q* in pieces of different sizes, the plate 735 is arranged to receive any one of a set of contact-plates 762 (Figs. 40 and 41) which apply locating and advancing pressure to the edge of the piece to be fed. Considering a plate 762 for a particular size of filler-piece, it comprises a rear portion extending across the straight edge of the lowest sole in the magazine, and arms 764, 764 which project forwardly along the stack parallel to each other. Curved edges of these arms may be forced down below slightly overhanging portions of lugs 768, 768 upon the plate 735, while the rear portion is laterally positioned by engagement with finished walls upon said plate. A pin 770 in this main plate may enter either of two slots 772, 772 at the outer edges of the arms. This engagement with the pin holds the plate 762 in the correct relation longitudinally of the filler-pieces. At the center of the rear of the plate 762 is a projection 774 arranged to enter the depression *q* of the bottom filler-piece in the stack. When thus engaged, the rear portions of the forepart of the filler-piece, which curve out from the shank, contact with inclines 776 and 778 formed at the ends of the arms 764. The wall 776, lying at a less angle than its companion to the axis of the filler-piece, corresponds to the outside of said piece, while the wall 778 is adapted for engagement with the inner side. Their joint effect is to swing, if necessary, the piece about the projection 774 until, by its contact at three spaced points, it is so positioned that its axis agrees with that of the sole which has been brought by a support 65 to position D. When one side of the contact-plate is upmost, it thus locates a left filler-piece, as appears in full lines in Fig. 40. When reversed, or turned face for face, it is adapted to act upon right filler-pieces, as indicated by dotted lines. The dimensions of the contact-plates 762 and their location upon the delivering plate may be such that, for each size of filler-piece, the projection 774 will be spaced outwardly from the magazine-bar 712 as it is adjusted for the size, and therefore in its relation to the depressions *q* in the contained filler-pieces, while the walls 776 and 778 are similarly separated from the curved edges of the forepart of the filler-pieces. There is thus given ample clearance for the pieces of greatest size to descend in the magazine between the surfaces 774, 776 and 778 of the plate 762 which are to position them. Then when the plate 735 travels forward in its delivering

movement, this plate first moves along the bottom filler-piece until the projection 774 enters the depression q , and the forepart is swung into correct angular position, retained 5 by the walls 776 and 778. Thereafter said filler-piece is carried in unvarying relation by the plates until it arrives at the delivery-point over the support 65.

Frictional contact of the delivering plate 10 with the bottom filler-piece resting upon it is considerable, so that, when the advance of the plate begins, it might start the movement of the filler-piece before it is engaged by the projection 774. To avoid this, the upper face 15 of the delivering plate is recessed to receive a supporting plate 780 (Figs. 40 and 41) of such size and so located that there is contact with it of the major part of the bottom filler-piece. The size of the recess containing the 20 plate 780 is such that movement of said plate in it is permitted to an extent at least equal to the initial engaging travel of the projection 774 toward the depression q . Shifting of the plate 780 in its recess is shown as limited 25 by a downward projection at its under side moving in a slot 782 formed in the delivering plate. As a consequence of the preceding feeding movement, plate 780 will, at the beginning of the inward travel of the plate, lie 30 at the inner extremity of its recess. Because the contact-surfaces of the plates 735 and 780 may be well lubricated and therefore offer little frictional resistance, the bottom filler-piece will remain stationary, holding the 35 plate 780 in contact with it, while the delivering plate at first advances. This continues until the projection 774 enters the depression in the filler-piece, so that the forward movement of the filler-piece begins only when it is 40 firmly seated against said projection. To further insure the desired positive engagement of the plate 762 with the delivered filler-piece, there is mounted at the forward extremity of the magazine, upon a bar 784 joining 45 the uprights 710 (Fig. 37), a spring-plate 786, the curved inner end of which drags over the upper surface of each filler-piece as it is fed from the magazine, and thus retards its progress. This holding back of 50 the object fed unfailingly causes the projection 774 and surfaces 776 and 778 to firmly engage and initially locate the filler-piece for its correct delivery.

Bridging the space between the central 55 standard 61 and the cross-bar 708, above the stopping place of the supports 65 at position D, is a bar 788 (Fig. 36), which has guided in it a vertical rod 790, carrying at its lower end a pressure-head 792. This head is to 60 cause the formation of the delivered filler-piece to the contour of a sole upon the support and the adhesion between the two elements. The pressure-surface of this head is furnished by a block 794 (Figs. 36 and 37), 65 preferably of yieldable material, as rubber,

adapting itself readily to the objects with which it contacts. The contour of the pressure-surface is, like the co-operating surface of the support 65, a mean between the various sizes of right and left soles which are to be operated upon. The block 794 is shown secured to a backing 796, conveniently of wood, which may be, in turn, fixed to a mounting-plate 798 seated in a depression in the head. To render the pressure-surface readily removable for substitution or renewal, the plate 798 has a stem 800 (Fig. 43) entering a cylindrical recess in the head. The upper end of the stem is slotted to permit it to pass the reduced portion 802 of a plunger sliding horizontally in the head. At one side of the slot, the stem has a bore to receive the enlarged extremity 804 of the plunger. A spring 806, compressed between the end of a depression in the head and a finger-piece 808 upon the outer extremity of the plunger, maintains the enlargement 804 in normal engagement with the bore and the stem. To release the pressure member from the head, it is only necessary to press the finger-piece 808 inwardly, this freeing the stem from the plunger and permitting it to be withdrawn from the head-recess. 70 75 80 85 90 95

From points near the opposite ends of the pressure-head rise rods 810, 810 guided in the bar 788 and preventing the rotation of the head about the axis of the central rod 790. Between nuts upon the upper ends of the rods 810 and the top of the bar are located springs 812, surrounding the rods and acting to restore the head to normal position after its pressure-applying movement. Carried upon the top of the bar 788 is a vertical cylinder 814, into which the rod 790 extends and has fixed upon it a piston 816. Air is periodically admitted to the cylinder to lower the pressure-head against the force of the springs 812 and bring about contact with the sole-elements upon the support, this air being supplied from the pipe 409 through 100 pipes 410 and 818 (Fig. 29). Primary control of this air-pressure is by a valve 820 (Figs. 26 and 27), included in the piping 818 and having its rotatable body 822 fastened upon the shaft 552 at position C, the 105 rate of rotation of this shaft being suitable for the purpose of actuating the valve. After the delivered filler-piece has been placed over the support, ready to receive the action of the head 792, the valve opens the pipe 818 by connecting the inlet and outlet through a recess 824 in the body, and applies pressure for a predetermined length of time. The air-supply is subject to other or secondary control-actions introduced to make certain that the elements have attained the proper relation. These will be described in connection with the mechanisms through which they are actuated. 110 115 120 125

A filler-piece having been advanced over 130

the support by the delivering plate 735, it must be removed to allow the withdrawal of the plate and the action of the pressure-head. Referring particularly to Figs. 37 and 38, there are guided for vertical movement through openings near opposite ends of the head, plungers 826, 826 (Fig. 38), at the lower ends of which are reduced portions or impaling points 828 for engagement with the filler-piece upon the plate and for its temporary retention. A spring 830 is situated within a bore in each plunger, with its upper extremity bearing against an overhanging bracket 832 attached to the head. Each plunger may be latched up, with its spring under compression, by a detent 834 pivoted upon the bracket and forced into engagement with a series of ratchet-teeth 836 on the squared upper portion of the plunger. Another squared surface may contact with the bracket to serve as a guide and hold the plunger against rotation about its axis. To yieldably effect this detent-engagement, each has bearing against a downwardly extending portion 25 a spring 838 (Fig. 37), backed by a collar 840 secured to a rod 842 arranged to slide horizontally upon the top of the head. The collars 840 and springs 838 are urged toward their respective detents by a spring 844 (Fig. 40), also surrounding the rod and abutting against a collar 846 thereon and against an upstanding portion of the head in which it slides. Because of the presence of the springs 838, the detents may act independently in 30 their engagement of the ratchet-teeth, unaffected by the position of the companion detent. To release the plungers so they may be forced down by their springs, the detents are rocked away from the ratchet-teeth by the contact of collars 848 upon the rod 842 with the sides of the detents opposite the springs 838. A shifting of the rod to the right, as viewed in Fig. 37, effects this release and is accomplished by the plate 735 at the termination 35 of its delivery-travel. Fulcrumed upon one end of the head is a lever 850, the upper extremity of which is aligned with and receives the contact of the rod 842, the pressure of this rod holding the lever against a stop-pin 852 projecting from the side of the head. The lower end of the lever carries a contact-portion 854 lying in the path of the delivering plate. When this plate is on the point of terminating its travel below the pressure-head, 40 it strikes the contact-portion of the lever, swinging this in a clockwise direction (Fig. 37). The lever is thereby forced against the rod 842, which is carried to the right against the expansive force of the spring 844. As a result of this, the collars 848 contact with the detents 834, which are thereby moved out of engagement with the ratchet-teeth upon the plungers 826. Thus released, the springs 830 urge the points 828 sharply down into a 45 filler-piece upon the delivering plate. The rack 738 and its gearing then withdraw this plate, leaving the filler-piece held by the points of the plungers above the support 65. To cause one or both of the pins 852 to enter the filler-pieces more deeply and thus exert a greater retaining effect, the supporting plate 780 may be grooved out below the pins, as is indicated at 855 (Figs. 40 and 41). Over this groove, the pins, when forced down by their springs, do not encounter the plate, and therefore pass entirely through the filler-piece. To resist the impaling impulse of the plungers, the delivering plate, in its extreme position over the support 65, passes above and engages a horizontal surface 856 upon a bracket 858 carried by the standard 61 (Fig. 37). On this surface 856, the plate is guided by an incline 860, with which it may first contact. The points 828 lie normally within the ends of sleeves 862, which surround the plungers 826 and are yieldably held down by springs 864 about the plungers and abutting against a shoulder upon the sleeve and against surfaces of the head 792. A screw 866 holds each of the sleeves in place in the head against its spring, while permitting its removal. When the plungers are released by their detents, the points are carried below the ends of the sleeves. Then, when the head, under the influence of the pressure in the cylinder 814, forces the impaled filler-piece against the sole upon the support, the pins first yield, and thereafter the sleeves rise with them until both have passed above the pressure-surface of the block 794. Upon upward travel of the head, after completing the filler-piece-laying and forming operation, the plungers remain latched up by the detents, while the sleeves are forced down by their springs. They therefore serve, by their pressure upon the filler-piece, to strip this from the pins, counteracting any tendency of the latter to draw said filler-piece away from the sole. At the end of the outward travel of the plate 735 to its initial position, or after the completion of the filler-piece-delivering operation, an adjustable contact-screw 870 (Fig. 42) which it carries contacts with and opens a plunger-valve 872 in the pipe 818 (Fig. 29) between the source of air-pressure and the cylinder 814. In consequence of this, it will be clear that the pressure member cannot descend while the delivering plate remains in its path, but only when said plate is withdrawn and in its filler-piece-receiving position.

Between the time of laying the sole upon the support at position A and the application of the filler-piece at position D, something may have occurred to displace said sole angularly about the pin 66, so it will not be in the desired relation to receive its filler-piece. Therefore, a correcting action is applied to each sole to reposition it upon the support at D before the filler-piece is laid. Attached to the under side of the bar 788

is a cylinder 876 (Figs. 38 and 43) lying transversely of said bar and therefore of the support beneath it. Fulcrumed near opposite extremities of this cylinder upon a carrier member 874 (Fig. 37) mounted to slide on extensions 875 from the top of the cylinder are levers 878, 880, the lower ends of which have adjustably secured to them contact members 882 so arranged that their 5 serrated engaging faces 884 will simultaneously swing in oppositely to points at which the edges of the forepart of the narrowest sole upon the support should lie. To thus oscillate the levers, 878, which has an extended fulcrum, is joined by a link 886 to a piston 888 operating in the cylinder 876. A link 890 communicates movement from lever 878 to lever 880. Pressure to produce this 10 correcting movement of the levers is introduced into the cylinder 876, as determined by a rotary valve 892 in pipe 819, from pipe 409 through the piping supplying the cylinder 814 of the pressure-head (Fig. 29). The valve 892 is operated in the proper time-relation by a cam 894 (Figs. 36 and 38) turning 15 with the gear 740 and pinion 742. A roll upon the lower extremity of a lever 896 fulcrumed upon the standard 700 is engaged by the cam, while the upper end of the lever is joined by a link 898 to an arm 900 fixed to the 20 valve-spindle. During the reciprocation of the delivering plate, the cam 894 is oppositely oscillated through two complete turns. Therefore, as will be clear from the showing 25 of Fig. 38, the lever will be turned in an anti-clockwise direction, and the valve 892 opened when the delivering plate is moving out from the magazine. The consequent outward travel of the piston 888 simultaneously 30 swings the arms 878 and 880 downward into contact with the sole upon the support, and, if this has become displaced in either direction, restores it to its correct axial relation, the movement occurring about the pin 66 as 35 an axis. The angular adjustment of the sole is permitted by the yieldability and frictional engagement of the contact member 84, which holds its toe-end in place (Fig. 4). The extent of correcting movement of the 40 levers is the same for all widths of soles, sufficient to properly locate the narrowest. Wider soles hold the levers from taking the full inward swing, this being made possible by the compressibility of the air in the actuating system. Since, however, the levers are 45 maintained by the link 890 in the desired relation throughout their strokes, this does not impair their accuracy. The action just described leaves the lever 896 in its actuated 50 position with the valve 892 open. As soon as the rotation of the turret begins to carry the supports to the succeeding operating positions, an inclined contact-surface 902, carried at one side of the outer end of the arm 55 64 (Figs. 2 and 38), strikes a roll 904 jour-

naled upon the lever. The latter is by this means returned to its normal position, with its actuating roll resting against the reduced portion of the cam 894, as appears in Fig. 38. This lever-movement closes the valve 892.

As the inward sole-adjusting movement of the lever 880 approaches completion, it is taken advantage of to fully establish the connection of the source of fluid-pressure to the cylinder 814, and thus bring the pressure-head against the work while the latter is still under the influence of the adjusting levers. To an eye 910 mounted to turn in the lever 880 (Fig. 38) is joined a rod 912 articulated to a valve-piston 914 operating in a cylinder 916 carried upon the top of the bar 788. Pressure is admitted to the cylinder 814 when the piston 914 is lowered by the inward travel of the arm 880, this alining an annular groove 918 in the piston with ports in the cylinder, to which opposite sections of the pipe 818 are connected. Therefore, it is only after the true relation of the sole upon the support has been assured that the filler-piece can be pressed upon it by the head 792. In this admission of fluid-pressure to the cylinder 814, it may carry with it a lubricant which drips slowly from a cup 919 delivering to the pipe 818 just above the cylinder-head. This insures a tight joint at the periphery 95 of the piston.

To effectively turn the sole about the support-pin 66 in the manner previously outlined, it is best acted upon by the levers 878 and 880 at the forepart. Since the relation 100 of this portion of the sole to its longitudinal axis differs so greatly for rights and lefts, thus must be taken into account in the actuation of the levers. As has already been pointed out, these levers are fulcrumed upon 105 the sliding member 874. This member is joined at 920 to a lever 922 (Fig. 40) fulcrumed by a link 924 to the bar 788 (Fig. 36). The opposite extremity of the lever is connected by a link 928 to the sliding frame 706 110 of the magazine. The elements are so proportioned and united to one another that, when the toe-engaging wall 704 of the magazine is adjusted for a right or a left filler-piece and secured in place by the latch 734, a 115 like movement is imparted to the carrier member, to the correcting levers 878 and 880 and to the piston 888. This results in their properly locating either sole to symmetrically receive its filler-piece.

The descent of the head 792 with the impaled filler-piece, and the forcing of this piece upon the sole having been accomplished by the pressure admitted to the cylinder 814 through the operation of valves 820, 872 and 125 916, the fluid in the cylinder must be exhausted to enable the springs 812 to elevate the head in preparation for its next operation. This is shown as accomplished through a pipe 930, in which is a normally closed 130

plunger-valve 932 situated at position E (Figs. 52 and 29). Upon a horizontal shaft 934 (Fig. 45) journaled in the central standard 61 and in another frame portion, which 5 shaft is rotated in the desired time-relation, is fixed a cam 936, acting upon a lever 938 fulcrumed upon a bracket 939 fixed to the frame. The opposite or upper extremity of the lever, when moved by the cam, opens the valve 932 10 to cause the exhaust of the cylinder 814. At the same time, exhaust from the cylinder 876 occurs, the piston 888 and levers 878 and 880 being returned to normal by a spring 940 (Fig. 40) surrounding a rod 942 mounted in 15 a projection 944 from the piston, this spring abutting against a nut threaded at the end of the rod and against a lug 945 in which the rod is guided upon the carrier 874.

Associated with the filler-piece-magazine 20 is stack-testing mechanism, which may resemble that employed in connection with the stack of shank-pieces at position C. Fulcrumed upon the column 714 is a lever 950 (Fig. 40) carrying a finger 952 movable 25 against the filler-pieces at a suitable height above the bottom. The finger receives its testing oscillation through a slide 954 mounted upon the top of the standard 700, a connecting-rod 956 articulated to the slide, and 30 a bell-crank lever 958 turning about the spindle 614 at position C (Fig. 31). A roll 960 upon the lever is drawn against the periphery of the disk 536 by a spring 962, similarly to the lever 616 which tests the stack 35 of shank-pieces. When the disk-depression 626 arrives at the roll 960, the finger 952 may either be allowed to move idly against the stack of filler-pieces, held thereby from producing any effect; or, if these filler-pieces 40 have fallen below the desired minimum, the finger will travel farther in, so that the outer end of a slot in the lever 958 contacts with the pin 628 of the rod 630. In this case, precisely as in connection with the shank-test- 45 ing finger 624, the valve 642 is opened by the turning of the shaft 634, and the clutch 276 at position A is disconnected to stop the supply of soles. This will lead to a replenishing of the filler-piece-magazine, since until 50 this is done the machine can only operate to complete the soles which have already been supplied. It will be evident that the slotted connections between the levers 616 and 958 and the pin 628 permit the actuation of 55 the valve 640 by either lever without interference with the other. To avoid disturbance of the filler-piece-testing mechanism by the adjustment of the magazine-bar 712 through the screw 724 and its connections, 60 the lever 950 is joined to the slide 954 by a slot-and-pin connection 964 (Fig. 40). In consequence of this, wherever the column 714 may be adjusted, the pin remains in the slot, and the lever and slide in effective associa- 65 tion.

Operating position E—work-removing mechanism—(Figures 45 to 52, inclusive)

At E, the last position of the machine, the travel of the support 65 bearing the completed composite sole is stopped by the Geneva mechanism 150, 152 opposite a standard 970, having extending across its top a table 972 supporting a series of sole-receiving boxes or receptacles 974 (Figs. 45 and 47). 70 These are to be successively advanced into alinement with the supports at this position as preceding boxes are filled with soles taken from said supports. Each of the boxes is shown as having a bottom wall and vertical 75 inner end and side walls, the outer end being open, save for a low wall 976 carried upon the bottom of the box and upon which the rear portions of the soles of the contained stack are supported to maintain them in proper 80 position for transfer. Upon a bracket 978, opposite the receiving position, is mounted a vertical bar 980 to retain the work in the boxes during its delivery. To permit of this 85 bar being adjusted for different lengths of soles, it may be variably held by a screw 982 passing through a slot in an angular support, which forms a part of the bar, and being threaded into the bracket 978.

The transfer of the soles one by one from 90 the supports 65 to the boxes is effected by a work-grasping device 984, which may be, in most respects, that made the subject of United States Patent No. 1,438,482, December 12, 1922. This grasping device is mounted 95 upon a bar 986, and has normally separated fingers 988 forced beneath the sole by contact of a portion 990 with the upper surface, and latched in this grasping position by a member 992. Similarly, for example, to 100 the transferring mechanism at position A, the bar 986 is oscillated between the support and receiving box by a parallel motion including arms 994, 994 fixed upon shafts 996 journaled in a vertical extension 997 of the standard 970, and connected at their outer 105 ends by a vertical bar 998. Segmental gears 1000, fixed to the shafts, mesh with a vertical rack 1001 reciprocated by connections 1002 from a crank 1004 upon the shaft 934. This 110 shaft 934 may be continuous, instead of sectional, as are the corresponding shafts at the companion positions, and is driven uninterruptedly when the machine is in operation, through the bevel-gearing 165 from a 115 vertical shaft 1010, which is rotated by the sprocket-gearing 164 from position A. The bar 986 is carried upon an outwardly and generally horizontally extending arm 1012 (Fig. 45) from the bar 998 of the parallel motion, and has secured to it, above the grasping device 984, an arm 1014, which is slotted 120 to receive a pin 1016 projecting horizontally from a downward extension of the bar 998. A friction device 1017, associated with the 125 130

pin 1016, bears against the arm 1014 of the bar 986, so that this will be yieldably retained in whatever position it may be placed within the limits of the slot. The latch 992 for the 5 grasping device is shown as pivoted at 1018 upon the bar 986, and having an arm 1020 joined by a link 1022 to a lever 1024 fulcrumed at 1026 upon the upper side of the carrier-arm 1012, which is a part of the parallel motion. A screw 1028, threaded vertically through the extremity of the lever 1024 opposite that to which the link 1022 is connected, is arranged to contact with what 10 is then the top side of the upper arm 994 of the parallel motion when this reaches the delivery position over one of the boxes 974. This engagement depresses the link 1022, and swings the latch 992 free from its retaining engagement with the grasping arms to release these and thus free the transferred sole.

To exert a direct upward pull by the transferring mechanism upon the end of the sole, as that containing the opening σ , so that it may leave its support without binding upon the pin 66, there is associated with the fingers 988 a lifting claw 1030. This claw is preferably fixed upon the lower end of a rod 1032 vertically adjustable in a fitting 1034, which may be arranged to swing upon the 25 pivot 1018 of the latch 992. A screw 1036 is shown as threaded through the fitting, and engages the latch. When the latch is in its outward position, so that the fingers 988 are separated from one another in readiness to 30 grasp a sole, the contact of said latch with the screw 1036 holds the claw clear of the vertical plane of the sole-end. As the latch moves in to its retaining position after the fingers have grasped the sole, the claw is 35 caused by gravity to swing with it, positioning itself beneath the end of the sole. Consequently, when the grasping device rises, the claw exerts an almost straight upward pull upon the sole-end parallel to the axis 40 of the pin 66 and in close proximity thereto. All tendency of the sole to bind is therefore 45 counteracted.

Because of the engagement with the end of the sole of the claw, it is important that, as 50 the location of the support-pin 66 is changed through slide 224 for different sizes of soles, the grasping device shall be correspondingly changed. Upon the outer extremity of the arm 1014 is carried a roll 1040 (Fig. 45), 55 which, as the device 984 descends to grasp a sole upon the support, enters a controlling guideway 1042 formed between opposite members 1044 of the device 608. This device has already been mentioned because of its inclusion in the train of connections between the hand-wheel 232 at position A and the contact-bar 594, which locates the shank-transferring mechanism at position C. The members 1044 are movable along the arm of the 60 bracket 488 on the standard 61, they having

threaded openings to receive the screw 612 rotatable by the gears 610 when the hand-wheel 232 is turned (Fig. 53). The guideway is curved on the arc imparted to the roll 1040 by the parallel motion, and has, at its upper end, a throat furnished by inclined surfaces 1048 on the members 1044. If, when the size-adjustment is made by the hand-wheel 232, the roll is within the guideway, this causes the arm 1014 to be shifted along 70 the pin 1016, and the grasping device, with the claw 1030, adjusted upon its carrier in correspondence with the pin 66. Were the roll 1040 outside the guideway at the time of adjustment, it would, upon its sole-engaging movement, encounter one or the other of the inclines 1048, and would thus be directed into the correct relation, as determined by the adjusted position of the members 1044.

In preparation for the transfer of the sole, 80 the toe-retaining member 84 of the support 65 is released by contact of the roll 118 with a cam-surface formed upon a member 1049 mounted upon the frame (Fig. 45). The cam-surface forces the lever 80 inwardly until its stud 104 is at the inner side of a vertical line through the engaging end 102 of the latching lever 100. This withdraws the member 84 from contact with the edge of the sole. In its movement, the lever 80 engages the end 90 90 of the lever 90, and thus removes the hooked end 88 from above the sole, which is thereby completely freed to be taken from the support by the transferring mechanism.

As the transferring mechanism at position E is allowed to operate continuously, the support-roll 116 here exercises no control over the driving mechanism, but it is utilized to definitely determine the angular relation of the turret in its stopped position to correctly 100 align the supports with the various operating mechanisms. Secured to the standard-extension 997 is a bracket 1050 (Figs. 51 and 52), 105 in which is guided a vertical slide 1052 provided with a head 1054, forced to a predetermined maximum height by a spring 1056 seated beneath the slide within the bracket. The head has a central depression between opposite upwardly converging inclines 1058, 1058. The incline upon the side from which the roll 116 approaches is so located that this roll, in its travel, strikes it and forces down the slide against the spring. Just as the roll settles into the depression against downwardly converging walls 1060, the Geneva mechanism 110 stops the turret, and the co-operation of the head 1054 with the roll centers the turret, counteracting the effect of lost motion in the actuating mechanism. When the turret is again started by the Geneva mechanism, engagement of the roll with the wall 1060 at the side toward which it travels cams down the slide 1052, so that the roll is released from its engagement.

Through a slot in the table 972 operates a 115 120 125 130

sprocket-chain or endless conveyor 1062 supported at one extremity by a sprocket-wheel 1064 (Fig. 47) fixed to a shaft 1066 rotatable upon a bracket 1067 beneath the table, 5 while at the opposite end the chain passes over a sprocket-wheel 1068 arranged to turn about a spindle 1070 projecting from one side of a bracket 1072 depending from the table (Fig. 45). The bracket 1067 10 is preferably mounted for adjustment longitudinally of the table by means of a slot-and-screw connection 1073 permitting the proper tension of the sprocket-chain to be maintained. Included as links of the chain 15 are outward projections 1074, which pass through the table-slot and are uniformly spaced from each other a distance sufficient to admit between them the boxes 974, so said boxes may be moved over the table when 20 the chain is actuated. In this travel, the upper run of the chain is maintained horizontal by a surface 1076 of the table. Secured to the under side of the table is a casting 1077, in which is shown, formed integrally, 25 a cylinder 1078. Within the cylinder operates a piston 1080, to the rod 1082 of which is fastened a head 1084 (Figs. 47 and 48) sliding in ways in the casting. Pivoted upon the side of the head is a detent 1086 arranged to 30 engage the chain-projections 1074, and being forced toward these by a spring 1088 interposed between the detent and the head. The chain is retained against displacement under the pressure of the detent by a vertical 35 wall 1090 upon the casting.

It is desired to receive in each of the boxes 40 the same number of completed soles, and therefore to operate the chain periodically through a distance sufficient to remove a box from the receiving position, and bring the succeeding box into its place. The length of the periods between the changing of the boxes is determined by counting the operations of the transferring mechanism by means 45 of connections to the shaft 934, which rotates once for each delivery of a sole. In the present instance, forty-eight soles is the number to be received in each box, and the shaft 934, through worm-gearing 1092 (Figs. 51 50 and 52), for each forty-eight times it rotates, turns once a cam-wheel 1094. The cam-wheel rotates about a spindle 1096 projecting from the bracket 939, and has a cylindrical contact-surface broken by a depression 1098. Upon 55 the contact-surface of the cam rides a roll 1100 carried by a lever 1102 fulcrumed upon the bracket 939. A spring 1104 between the bracket and lever forces and adjustable contact-screw 1106 toward the head of a plunger- 60 valve 1108 included in a pipe 1110 which leads (Fig. 29) from the pipe 411 to the cylinder 1078. The valve is normally closed, and the lever is prevented from operating it by the engagement of the cylindrical portion of the 65 cam with the roll 1100. When the depression 1098 approaches the roll 1100, a contact-plate 1112, attached to a face of the cam and having an angular portion extending into the depression, receives upon its outer edge the engagement of a squared head 1114 on the roll-spindle. This continues to hold the lever 1102 away from the valve until the end of the forty-eighth operation of the transferring mechanism following the preceding actuation of the chain 1062. Then, travel of the 70 corner of the plate 1112 past the head 1114 permits the roll to drop abruptly into the cam-depression under the influence of the spring 1104, and the valve to be opened by the contact-screw. Compressed air from the 75 source therefore enters the cylinder 1078, forcing the piston to the right, as viewed in Fig. 47, and, by the engagement of the detent 1086 with one of the chain-projections, shifting the filled box from the receiving position, and bringing the succeeding box into 80 its place. The soles may then be removed from the box thus advanced, and it returned to the chain at the opposite end of the series. 85 To prevent the chain from being moved too suddenly and forcibly, the pressure may be throttled to the necessary extent by a needle-valve 1116 (Fig. 50) contained in the fitting through which the pipe 1110 delivers to the cylinder. The travel of the piston, and therefore of the chain and boxes, is shown as variably limited by a stop-screw 1118 (Fig. 47) threaded through the end of the casting 1077. 90 This screw the head 1084 strikes at the completion of its feeding movement. The piston is returned to its initial position by a spring 100 1120 encircling a rod 1122 fixed to the head and guided beneath the casting. The exhaust from the cylinder, following the closing of the valve 1108 as the depression 1098 105 leaves the roll 1100 and the spring 1120 is permitted to act, may be by leakage about the stem of the valve, there being ample time for this to take place before another group of soles has been received. The chain and boxes 110 are prevented from being thrown past the desired points, and are held against movement during the idle stroke of the detent 1086, by a brake-band 1124 mounted beneath 115 the table and frictionally engaging a drum 1126 formed with the sprocket 1068.

Just beyond position E, there is supported upon the standard-extension 997 a member 1130 (Figs. 45, 51 and 52) having a cam-surface 1132 arranged to contact with the roll 78 of the work-support to press it upwardly. This releases the slide 67 and pin 66, so that they are moved out by the spring 68 to the setting for the largest size of sole. Thus freed, the pin is reset for the sole-size to 120 which the index-point is adjusted upon graduations 236 at position A by rotation of the hand-wheel 232. To effect this, the roll 70, in its continued movement from position E, 125 contacts with an inclined surface upon a 130

member 1134 (Figs. 5, 6, 10, 11 and 53) secured to the end of a rod 1136 projecting from the extension of the slide 224. By the rotation of the hand-wheel, the contact member 1134 is moved proportionately to the other elements which are simultaneously adjusted, so that, upon engagement of the roll 70 with the surface, the pin 66 is carried in to the correct position for the particular size to be operated upon. The roll 78 has at this time passed the surface 1132, and the camportion 74 re-engages the slide 67 to secure this in its new position. To elevate the pin 108 after the finished sole has been removed from the support, the end of the slide 114, carrying the roll 116, travels over a cam-surface 1138 upon the member 1130, this occurring while the lever 80 is still held back by the member 1049. As the pin 108 rises, the inner extremity of the latching lever 100 is permitted to drop, so it comes into co-operation with the stud 104. The spring 113, which has been below the axis of the lever 112, maintaining the pin in its lowered position, is now transferred to a point above the axis, thus holding the pin raised. When the roll 118 advances beyond the member 1049, the lever 80 is released and carried by its spring against the retaining end 102 of the lever 100. All the elements of the support are now restored to their normal positions ready for the succeeding operation.

Outline of the operation of the machine

35. There will now be given a brief summary of the action of the entire machine with reference to the elements more closely associated with the work and the principal parts operating or controlling them.
40. To prepare the machine for its automatic action, the sole, shank-piece and filler-piece magazines at positions A, C and D, respectively, are filled, and cement placed in the receptacle 428 at position B. A source of constant air or other fluid-pressure is connected to the pipe 409, and the circuit supplying electricity for the heating units 433 at position B is closed. When the heat generated by the units has become sufficient to render the cement at the nozzle 432 properly fluid, the motor 130 may be started. This puts into operation the driving mechanism for the turret carrying the five work-supports 65, which moves with predetermined intervals of rotation and rest, under the control of the Geneva stop mechanism 150, 152, and also furnishes power for the mechanisms at the five operating positions. The operations occurring at each of these positions will be followed for the work carried by a single support, bearing in mind that, in connection with each of the other four supports, operations are simultaneously occurring peculiar to the particular position at which each support is then located.

A support entering position A without a sole upon its receiving surface has had the lever 80 of the retaining device drawn back at the preceding position and latched by the lever 100, the pin 108 of the central support being projected above the receiving surface, and the controlling roll 116 being at its inner position. The pin 66, for entering the openings of the soles and shank-pieces and the filler-piece depressions has also been set adjacent to the succeeding position by action upon its roll 70, and has been locked by the lever 72. The position of this pin 66 is determined by the cam member 1134, set by the operator through rotation of the hand-wheel 232 until the scale 236 and co-operating index-point indicate the particular size of sole to be operated upon. Simultaneously this setting correspondingly locates the end walls 204 and 206 of the magazine 199 at position A; fixes the relation of the end of the strip *c* of cement to the support-pin 66 at position B; provides for registration with said pin of the shank-piece openings *p* when said shank-pieces are deposited by the transferring device 572 at position C; adjusts the bar 712 of the filler-piece magazine 702 at position D; and arranges the transferring device 984 to correctly grasp a completed sole upon the support at position E. In connection with this train of adjustments, which the operator effects through the hand-wheel, he also, with the aid of the graduated bar 252, sets the gage-bar 238 of the magazine at position A for the width of the soles, and at position D puts in place a contact-plate 762 upon the delivering plate 735, this contact-plate corresponding to the size of the filler-piece and being arranged for a right or left, as may be necessary. He further, at position D, locates the magazine-wall 704 for a right or left filler-piece, securing it by the latch 734. This latter operation simultaneously arranges the sole adjusting levers 878 and 880 for action upon a right or a left sole.

At position A, the roll 116 causes the actuation of the driving clutch 276 at this position. As a result, the transferring mechanism 344 engages a sole *S* which has been advanced from the magazine by the slides 268 and 281, and aligned laterally and adjusted into correct longitudinal relation by the fingers 304, 304 co-operating with the gage-wall 340. The engaged sole is then conveyed by the movement of the transferring device to the support 65, where its pressure upon the pin 108 trips the latching lever 100, releasing the lever 80 and causing the retaining device carried by it to move against the sole to hold the toe-end upon the support for the succeeding operations. At the same time, the lever 90 is actuated by lever 80, so the hook 88 passes over the heel-end of the sole to retain its against upward displacement. The transferring device then swings back to its

initial position to engage the succeeding sole fed from the magazine 199, and the support travels forward to position B. Continuously during the sole-feeding and transferring operations, the finger 398, actuated by the feeding slide 268, is testing the stack of soles in the magazine to determine whether there is a suitable supply. If the level falls below a predetermined minimum, the air-valve 408 is opened, and the plunger 413 caused to unlatch the rod 387, and thus disconnect the clutch 276 and stop the sole-supply to warn the operator of the condition.

If for any reason no sole has been placed upon the support, the pin 108 will not have been depressed, and the roll 116 will remain at its innermost position. It does not, therefore, strike the controlling means for the driving mechanism at position B or any of the succeeding positions, and no operations occur until the defect has been corrected. But a sole being in place, and the roll 116 forced outwardly as a result, the controlling lever 498 of the driving mechanism at position B is freed to start the action. The cement-receptacle 428 is moved forward and then returned, carrying its nozzle along the surface of the sole, the adhesive flowing through said nozzle when the valve 436 controlling the supply from the receptacle is opened. This opening occurs, first through the surface 432, at the termination of the inward travel of the receptacle, acting upon the roll 458 and producing the spot *a* upon the forepart of the sole; then, upon the opposite movement, by the surfaces of the rod 423 contacting with the roll 460 between the depressions 479 and 478, giving the cement-strip *b*; and between the depressions 478 and 477 making the shorter strip *c*. The cement-receptacle having been returned to normal by the driving mechanism, and the valve closed by the dropping of the roll 460 into the depression 477, the support advances to position C, governed by the Geneva mechanism.

Again the roll 116 starts the driving mechanism, causing the transferring device 572 to lift a shank-piece *s* from one of the slots 540 in the delivering disk 536 and lay it upon the cemented strips *b* and *c* of the sole on support 65. The disk-slot has brought a shank-piece from the bottom of the stack in the magazine 511, said shank-piece being held against displacement by the magnetism of the supporting blocks 541. If the shank-piece should be missed by the transferring device and remain upon the disk, it will be displaced by the ejecting member 576 before it can injure the magazine by being carried against this. A test of the height of the stack of shank-pieces in the magazine is periodically made by the finger 624, and when this stack becomes unduly lowered, the supply of soles is cut off, and the operator notified of the condition

through the operation of the valve 642 governed by the finger and admitting air-pressure to the cylinder 412 to separate the elements of the clutch 276 at position A. If the transferring device 572 leaves its receiving position at the disk 536 without a shank-piece, its member 650 will be allowed to drop into the plane of the member 652. The resulting contact causes the rod 670 at the filler-piece-laying position D to be released to disengage the clutch 645 similarly to the action at position A. This prevents a sole from going through the machine with its filler-piece concealing the fact that a shank-piece is missing.

Upon the succeeding movement of the support to position D, the operating mechanism is thrown into action by the roll 116 to cause the delivering plate 735 to carry the lowest filler-piece *f* from the stack in the magazine 702 beneath the pressure-head 792, the plate there releasing, by engagement with the lever 850, the latches for the plungers 826, allowing the holding points 828 to be forced into and retain the filler-piece, while the slide is withdrawn. The maintenance of a supply of filler-pieces in the magazine 702 is made certain by the action of the finger 952. This responds to the descent of the stack below its level, and governs the same valve 642 as does the shank-piece-testing finger 624 to stop the feed of soles at position A. Before the head 792 descends to force the filler-piece which it carries against the sole resting upon the support, said sole is trued angularly about the pin 66 by the inward movement of the levers 878 and 880, actuated by air admitted to the cylinder 876 by the cam-controlled valve 892. At this time, the rotatable valve 820 has been positioned to open communication from the source of pressure for the actuation of the head 792. If all is ready for the application of the final assembling pressure, the valve 872 in the communicating piping between the pressure-source and the cylinder will have been opened by the return of the plate 735 to normal after the delivery of a filler-piece, and valve 916, also in the connections, actuated after the levers 878 and 880 have completed the adjustment of the sole and while it is still held thereby. Air is thus admitted to the cylinder 814, causing the descent of the head. The filler-piece upon the head is thereby pressed into contact with the cemented sole and superposed shank-piece upon the support, and all three forced together to form the composite sole.

The assembling of the work-pieces having been completed, the support moves the finished article to position E. Here the roll 116 engages the head 1054 to correctly locate all the turret-supports with respect to the transferring and operating mechanisms. As it approaches this position, the roll 118 is actuated

upon by the cam member 1049, so that the sole is freed from the member 84 at the toe-end, and, as an incident to the movement of the member 84, also released from the hook 88 at the heel-end. After the turret has been stopped, the thus-released sole is grasped by the device 984, transferred over a box 974 and dropped therein. When the box is filled after a predetermined number of movements 10 of the sole-grasping device, it is automatically carried from its receiving position, and an empty box substituted by the travel of the sprocket-chain 1062. This is produced pneumatically by the introduction of pressure into the cylinder 1078, under the control of the valve 1108, actuated at the desired intervals by the counting gearing 1092 and cam 1094. As the work-support leaves position E after the removal of the completed sole, its roll 78 encounters the cam-surface 1132, unlocking the slide of the sole-engaging pin 66. This pin, in the further travel of the support, is set by the engagement of the slide-roll 70 with the cam 1134, which, 20 as already pointed out, has been adjusted, together with certain elements at other positions, for the particular length of sole which is to be next operated upon. Having thus been located, the pin is locked by the now-released lever 72, and the support is ready for the beginning of a new cycle at position A.

Herein are disclosed certain features and combinations described and claimed in the 30 copending application filed in the United States Patent Office in the name of Frederick M. Furber on August 2, 1919, Serial No. 314,947. This matured on Nov. 13, 1928, into Patent No. 1,691,278.

Having described the invention, what is claimed as new and is desired to be secured by Letters Patent of the United States is:

1. The combination with a support for a sole-portion, of a member arranged to engage a sole-portion near one extremity and furnishing an axis about which said portion may be rotated, and retaining means for the opposite extremity of the sole-portion, said retaining means being organized to permit such rotation.
2. The combination with a support for a sole-portion, of a projection arranged to pass through an opening in said portion, and a frictional retaining member having a surface bearing against the opposite edge only of the sole-portion from the projection and being inclined downwardly and outwardly over said portion, said retaining member being organized to permit the sole-portion to be turned about the projection.
3. In a shoe machine, a support having a retaining projection extending from the supporting surface and arranged to pass through a supported sole-portion, and means movable over the supporting surface adjacent to the

projection and arranged to prevent the displacement of the portion from the projection.

4. The combination with a support having a projection from its supporting surface arranged to enter a sole-portion, of a lever fulcrumed upon the support and movable over the supporting surface adjacent to the projection. 70

5. The combination with a support for shoe-portions, of a plurality of movable retaining members for the work, one of said members being arranged to act upon another to affect its relation to the work, and operating means for each member, said operating means being independent of one another. 75 80

6. The combination with a support for shoe-portions, of a retaining member movable into engagement with one extremity of a supported portion, and a second retaining member co-operating with an opposite extremity of the supported portion and movable from said portion by the first-mentioned member. 85

7. The combination with a support, of a lever fulcrumed on the support and organized to retain work thereon, and a second lever fulcrumed upon the support and provided with a hooked end movable over the work, one of said levers contacting with the other to effect its actuation. 90 95

8. The combination with a support for shoe-portions, of a shoe-portion-engaging member arranged to permit angular movement of the portions upon the supporting surface, a retaining member arranged to frictionally resist such angular movement, and a retaining member arranged to prevent outward movement of the shoe-portion from the supporting surface. 100

9. The combination with a support having a projection therefrom arranged to enter an opening in one extremity of a supported article, of a lever fulcrumed upon the support and having a contact-surface for engagement with the extremity of the object opposite the opening, and a lever fulcrumed upon the support and having a hooked end movable over the article on the support. 105 110

10. The combination with a support having a projection therefrom arranged to enter an opening in one extremity of a supported article, of a lever fulcrumed upon the support and having a contact-surface for engagement with the extremity of the object opposite the opening, a lever fulcrumed upon the support and having a hooked end movable over the article on the support, and a spring arranged to actuate one lever and to draw said lever into engagement with the companion lever. 115 120 125

11. In a sole-assembling machine, a sole-support movable to a plurality of operating positions, a plurality of retaining members movable into engagement with the opposite extremities of a sole upon the support, sta- 130

- tionary means at one position for initiating the engaging movement of the members, and means at another position for initiating their withdrawal.
- 5 12. In a shoe machine, a container for shoe-portions provided with movable walls, means arranged to move a wall of the container, a guiding member for the wall in its movement, and connections from said guiding member to another wall to effect its movement.
- 10 13. In a sole-assembling machine, a container provided with opposite walls arranged to respectively position the heel and toe-ends of sole portions, a guide member for one of the walls, connections for moving said guide member, guiding means for the companion wall, and connections for transmitting movement of the guide member to the companion wall.
- 15 14. In a sole-assembling machine, a container provided with opposite walls arranged to respectively position the heel and toe-ends of sole-portions, a reciprocatory rod arranged to guide one of the walls, connections for moving said rod, a reciprocatory rod arranged to guide the companion wall, and a lever connecting the rods arranged to move the second oppositely to the first.
- 20 15. In a shoe machine, a plurality of variable mechanisms for operating successively upon shoe-portions, the elements of the respective mechanisms being arranged in groups spaced from one another, and means common to the mechanisms and arranged to adjust such spaced elements of said mechanisms to correspond to different shoe-sizes.
- 25 16. In a shoe machine, a plurality of variable mechanisms for operating successively upon shoe-portions, the elements of the respective mechanisms being arranged in groups spaced from one another, a member arranged to be set to correspond to different shoe-sizes, and adjusting connections from said member to spaced groups of elements constituting different mechanisms.
- 30 17. In a shoe machine, a support for shoe-portions movable to different operating positions, operating mechanisms at said positions, a member arranged to be set to correspond to different shoe-sizes, and connections to the member arranged to move elements at plural operating positions.
- 35 18. In a shoe machine, a stationary support provided with a movable wall arranged to engage a shoe-portion, a movable support having a projection arranged to enter a shoe-portion, a variable member for moving the projection, and connections between the wall and member for moving them together.
- 40 19. In a sole-assembling machine, a support movable to a plurality of operating positions and provided with a movable sole-engaging projection, a variable element for moving the projection, a table situated at one of the positions and having a movable sole-en-
- gaging element, connections between said elements, and operator-controlled means arranged to actuate the connections.
- 45 20. In a sole-assembling machine, a support movable to a plurality of operating positions and provided with a movable sole-engaging projection, means for moving the projection, a table situated at one of the positions, a wall movable upon the table, and means arranged to simultaneously shift the projection-moving means and wall in accordance with different sole-sizes.
- 50 21. The combination with a support having a movable pin and revoluble through a plurality of operating positions, of a variable member for moving the pin, a table at one position provided with a movable wall, operating mechanism at another position having a variable element, and operator-controlled means arranged to vary the pin-moving member, wall and element simultaneously.
- 55 22. In a shoe machine, a support for shoe-portions movable to different operating positions, operating mechanisms at said positions one of which includes a container, a member arranged to be set to correspond to different shoe-sizes, connections to the member arranged to vary the size of the container, and connections from said member arranged to vary an element of a mechanism at another operating position than that at which the container is located.
- 60 23. A container for sole-portions comprising a support, walls arranged to hold a stack of sole-portions upon the support, a member spaced from the support to an extent greater than the normal thickness of the portions in the container to permit the passage of said portions beneath it and being yieldable vertically toward and from the support, means for feeding the portions beneath the yieldable member, and means for preventing movement of said member in the direction of advance of the portions.
- 65 24. In combination, a container for shoe-soles comprising a support, walls arranged to hold a stack of soles upon the support, a retaining member arranged to engage the foreparts only of soles in the stack, said member being spaced from the support to permit the passage of a sole beneath it, and feeding means provided with vertical walls movable in close proximity to both sides of the retaining member for engagement with the forepart of the lowest sole in the stack.
- 70 25. The combination with a container for a vertical stack of shoe-soles, of a yieldable gage member mounted to move in a direction substantially parallel to a side of the stack, and feeding means provided with vertical walls movable in close proximity to opposite sides of the gage member.
- 75 26. A container for sole-portions comprising a support, walls rising therefrom, a guide member situated between the walls, a gage-

bar movable in the guide member and spaced from the support, and a spring interposed between the guide member and gage-bar.

27. In a shoe machine, a container comprising a support for shoe-portions and a plurality of yieldable members spaced from the support a distance greater than the normal thickness of the portions in the container to permit the passage of said portions from the container and spaced from one another to contact respectively with the heel-ends and foreparts of the shoe-portions.

28. In a shoe machine, a container comprising a support for shoe-portions and a plurality of yieldable members spaced from the support by different distances to permit the passage of a shoe-portion from the container, the member farthest from the support having its end adjacent thereto inclined outwardly from the container.

29. The combination with a container for a vertical stack of shoe-soles, of a yieldable gage member arranged to engage the foreparts only of soles in the stack and mounted to move in a direction substantially parallel to a side of said stack, feeding means provided with vertical walls movable in close proximity to opposite sides of the gage member, and a retaining member mounted to yield vertically in engagement with the heel-portions only of the soles in the stack.

30. In combination, a container for shoe-soles comprising a support, walls arranged to hold a stack of soles upon the support, a retaining member arranged to engage the foreparts only of soles in the stack, said member being spaced from the support to permit the passage of a sole beneath it, feeding means provided with vertical walls movable in close proximity to both sides of the retaining member for engagement with the forepart of the lowest sole in the stack, and a retaining member mounted to yield vertically in engagement with the heel-portions only of the soles in the stack.

31. In combination, a container for shoe-soles comprising a support, walls arranged to hold a stack of soles upon the support, a retaining member arranged to engage the foreparts only of soles in the stack, said member being spaced from the support to permit the passage of a sole beneath it, feeding means provided with vertical walls movable in close proximity to both sides of the retaining member for engagement with the forepart of the lowest sole in the stack, and a retaining member mounted to yield vertically in engagement with the heel-portions only of the soles in the stack, the retaining member being normally spaced farther from the support than the gage member.

32. In combination, a container for a stack of molded shoe-soles comprising a support having means arranged to hold the heel-portions of the soles at a higher level than

the foreparts, a gage member arranged for engagement with the foreparts only of the soles in the stack, a retaining member arranged for engagement with the heel-portions only of said soles and being normally spaced farther from the support than the gage member, means for mounting both members to yield in a direction substantially parallel to a side of the stack, and means for feeding the soles forward beneath the gage and retaining member.

33. In a shoe machine, a container comprising a support for shoe-portions and opposite walls rising from the support, in one of which walls is an opening through which shoe-portions may be fed, a member situated at the side of the container opposite the opening and arranged to elevate the shoe-portions above the general supporting surface, and a feeding member movable from the elevating member toward the container-opening.

34. In a container for molded articles, a table, a wall rising from the table and provided with a delivery-opening to which one edge of an article is presented, an upward extension from the table arranged to support the opposite edge of the article above the table, and a feeding member arranged to reciprocate through the wall adjacent to the extension and toward and from the delivery-opening.

35. In a shoe machine, a container for shoe-portions comprising a primary member movable against portions to force them from the container, and a secondary member movable upon the primary member and arranged to grasp therewith the delivered portions.

36. In a shoe machine, a container for shoe-portions comprising a primary member movable against portions to force them from the container, and a secondary member movable upon the primary member toward and from the portions to be delivered and substantially at right angles to the longitudinal axis thereof.

37. In a shoe machine, a container for shoe-portions, a primary feeding member, a secondary feeding member spaced from the primary member, means for forcing the members toward each other to grasp between them portions in the container, means for imparting a feeding movement to the members, and means respectively at the inner and outer extremes of movement of the members together for separating them to permit the portions to be received and delivered.

38. In a shoe machine, a container for shoe-portions, opposite feeding members, one of which is movable upon the other, means for forcing the members toward each other to grasp between them portions in the container, means for moving the members toward and from the container, and means with which a member contacts in its move-

ment toward the container to separate it from the companion member.

39. In a shoe machine, a container for shoe-portions, opposite feeding members, a spring for forcing the members toward each other, and means for moving the members toward and from the container, an element of the container contacting with one of the members in its movement to separate said members.

40. In a shoe machine, a container for shoe-portions, opposite feeding members, means for forcing the members toward each other to grasp between them portions in the container, means for moving the members toward and from the container, means with which a member contacts in its movement toward the container to separate it from the companion member, and means for moving one of the members into and out of the plane in which the portions are delivered.

41. In a shoe machine, a container for shoe-portions, opposite feeding members, means for forcing the members toward each other to grasp between them portions in the container, means for moving the members toward and from the container, means with which a member contacts in its movement toward the container to separate it from the companion member, and means for moving one of the members into and out of the plane in which the portions are delivered, the last-mentioned moving means being effective near both extremes of travel of the members.

42. In a sole-assembling machine, the combination with a container for sole-portions, of movable feeding mechanism including a pivoted contact member, a traveling setting lever co-operating with the contact member, and a member engaged by the lever to effect its setting action, said engaging member being maintained stationary during its control of the lever.

43. In a sole-assembling machine, the combination with a container for sole-portions, of movable feeding mechanism including a pivoted contact member, a traveling setting lever cooperating with the contact member, and a member having a surface into engagement with which the lever travels to effect its setting action, said member being provided with another surface along which the lever travels and which temporarily retains the contact member in its set position.

44. In a sole-assembling machine, the combination with a container for sole-portions, of movable feeding mechanism including a contact member arranged to move into and out of the plane of delivery, means for moving the contact member to effect delivery, and a member engaged by the contact member in such delivering movement and arranged to shift the contact member out of the plane of delivering movement.

45. In a sole-assembling machine, the com-

bination with a container for sole-portions, of movable feeding mechanism including a contact member pivoted to move into and out of the plane of delivery, means for moving the contact member to effect delivery, and a spring fixed relatively to the delivering movement, said spring co-operating with the contact member during its idle travel to carry said member out of the plane of delivery.

46. The combination with a container, of a primary feeding slide, a secondary slide movable upon the primary slide, a member for contact with the articles to be fed fixed upon the primary slide, a member for contact with the articles to be fed movable upon the secondary slide, and means for moving the slides together to effect the feed.

47. The combination with a container, of a primary feeding slide, a secondary slide movable upon the primary slide, a member for contact with the articles to be fed fixed upon the primary slide, a contact member pivoted upon the secondary slide, a lever fulcrumed upon the secondary slide and acting on the pivoted contact member to raise it into the plane of feed, and a member into engagement with which the pivoted member moves and arranged to lower said member.

48. The combination with a container, of a primary feeding slide, a secondary slide movable upon the primary slide, a member for contact with the articles to be fed fixed upon the primary slide, a contact member pivoted upon the secondary slide, a lever fulcrumed upon the secondary slide and acting on the pivoted contact member to raise it into the plane of feed, a member into engagement with which the lever moves, said member being arranged to actuate the lever and to temporarily lock it in the actuated position, and a member into engagement with which the pivoted member moves and arranged to lower said member.

49. In a shoe machine, means for operating upon shoe-portions, a container for a stack of shoe-portions to be operated upon, means for delivering shoe-portions from the container to the operating means and including a movable member, driving mechanism for the member, connections organized to allow the member to be displaced upon encountering excessive resistance, and means into co-operation with which the member moves and which is arranged to reset it to its normal position.

50. In a shoe machine, means for operating upon shoe-portions, a container for a stack of shoe-portions to be operated upon, means for delivering shoe-portions from the container to the operating means and including a movable feeding member, driving mechanism for the feeding member, frictional connections organized to slip and allow the feeding member to be displaced upon encountering excessive resistance, and means arranged to reset the feeding member in its movement.

51. In a shoe machine, means for operating upon shoe-portions, a container for a stack of shoe-portions to be operated upon, means for delivering shoe-portions from the container to the operating means and including a movable feeding member, a lever for moving the feeding member, driving mechanism for the lever, frictional connections for the driving mechanism and lever organized to allow said lever to be displaced, and means for resetting the lever.
52. In a shoe machine, a container for shoe-portions, a feeding member movable to deliver shoe-portions from the container, a lever for moving the feeding member, driving mechanism for the lever, frictional connections for the driving mechanism and lever organized to allow said lever to be displaced, and a resetting member at each extremity of the path of the lever into co-operation with which it may travel when displaced.
53. In a shoe machine, a container for shoe-portions, a feeding member movable to deliver shoe-portions from the container, a lever for moving the feeding member, driving mechanism for the lever, frictional connections for the driving mechanism and lever organized to allow said lever to be displaced, and a screw at each extremity of the path of the lever into engagement with which it may move when displaced.
54. In a sole-assembling machine, a sole-container, a feeding slide operating therein, a rotatable driving device, a lever having relatively movable sections, one section being joined to the slide and another to the driving device, and frictional connections between the sections.
55. In a sole-assembling machine, a sole-container, a feeding slide operating therein, a rotatable driving device, a lever having relatively movable sections, one section being joined to the slide and another to the driving device, frictional connections between the sections, and adjustable contact members acting upon the slide and its connected lever-section when they are displaced from their normal relation.
56. In a shoe machine, a container for a stack of shoe-portions, a feeding member movable in the container, and a member movable along the line of feed into contact with a shoe-portion after the action of the feeding member and constructed and arranged to straighten the stack.
57. In a shoe machine, a container for a stack of shoe-portions, a feeding member movable in the container, and a straightening member movable against the stack in a direction opposite to the feed.
58. In a shoe machine, a container for a stack of shoe-portions, a feeding member acting upon the lowest shoe-portion in the stack, and a straightening member movable against the bottom of the stack from a point outside the path of the portions fed, into said path.
59. In a shoe machine, a container for a stack of shoe-portions, said container having a space through which the shoe-portions are fed one by one and an opening of greater extent at the same side of the container as the feeding space, and a stack-straightening member movable in the opening.
60. In a sole-assembling machine, a container for a stack of sole-portions, said container having an opening at one side somewhat greater in width than the thickness of a sole-portion and a second opening of greater width in the same side, and an oscillatory stack-straightening member movable through the wider opening.
61. In a shoe machine, a container for a stack of shoe-portions, a reciprocatory feeding slide movable into the bottom of the container, and an oscillatory straightening lever movable against the bottom of the stack.
62. In a sole-assembling machine, a container for sole-portions, said container comprising a gage-bar and a wall having an opening at the same side of the container as the gage-bar, and an oscillatory member movable through the opening into contact with the contained soles.
63. The combination with a stack-container having a yieldable member past which objects are delivered from the stack, of feeding means movable toward and from said member, and a stack-straightening member co-operating with the yieldable member.
64. In a shoe machine, a container for a stack of shoe-portions, said container having a space through which the shoe-portions are fed one by one and an opening of greater extent, a member yieldable adjacent to the opening, and a member arranged to oscillate in the opening into contact with the stack.
65. In a sole-assembling machine, a container for sole-portions, said container comprising a gage-bar and a wall having an opening at the same side of the container as the gage-bar, a member movable in the opening across the side of the stack, and an oscillatory member movable through the opening into contact with the stack.
66. In a sole-assembling machine, a container for sole-portions, said container comprising a yieldable gage-bar, a wall having an opening at the same side of the container as the gage-bar, a yieldable member movable in the opening across the side of the stack, and an oscillatory member movable through the opening into contact with the stack.
67. In a shoe machine, the combination with a container for a stack of shoe-portions, of feeding mechanism co-operating with the container and including a reciprocatory member, and a contact member movable against the stack and actuated by the feeding mech-

anism during the movement of the feeding mechanism in one direction only.

68. In a shoe machine, the combination with a container for a stack of shoe-portions, of feeding mechanism co-operating with the container and including a lever, and a stack-straightening device having a portion engaged by the lever.

69. In a shoe machine, the combination with a container for a stack of shoe-portions, of feeding mechanism co-operating with the container and including a lever, and a stack-straightening device having a portion engaged by the lever near the end of its idle travel.

70. In a shoe machine, a container for a stack of shoe-portions, a support arranged to elevate one side of the lowest shoe-portion, a feeding member acting upon the elevated side of said lowest portion, and a member movable against portions of the stack after the feeding operation.

71. In a shoe machine, a container for a stack of shoe-portions, a support arranged to elevate one side of the lowest shoe-portion, a feeding member acting upon the elevated side of said lowest portion, and a member movable against portions of the stack at the elevated side after the feeding operation.

72. The combination with a container for a stack of soles, of means for feeding the soles from the stack, and straightening members movable against the stack in the direction of feed and opposite thereto.

73. The combination with a container for a stack of soles, of feeding means acting upon the stack, a straightening member arranged to contact with the foreparts of the soles, and a straightening member for contact with the heel-ends of the soles.

74. In a shoe machine, a stationary support provided with a shoe-portion-engaging member variable in position, a movable support having an engaging member variable in position, and means common to the members for effecting their variation.

75. In a shoe machine having a plurality of operating positions, means for conveying a shoe-portion from position to position, variable means for locating a shoe-portion at one position, variable means for operating upon the portion at another position, and means arranged to simultaneously effect such variations.

76. In a shoe machine having a plurality of operating positions, means for conveying a shoe-portion from position to position and having a movable shoe-portion-engaging element, variable means for moving said element, variable means for locating a shoe-portion at one position, variable means for operating upon the portion at another position, and means arranged to effect the variations simultaneously.

77. In a shoe machine, a plurality of vari-

able mechanisms for operating upon shoe-portions, a member arranged to locate a shoe-portion for the operations of the mechanisms, and means common to plural mechanisms and arranged to adjust said locating member and an element of an operating mechanism to correspond to different shoe-sizes.

78. In a shoe machine, a plurality of variable mechanisms for operating successively upon shoe-portions, one of said mechanisms including a container having a movable wall and a shoe-portion-locating member associated with said container, and means common to the mechanisms and arranged to adjust said container-wall, locating member and an element of another operating mechanism to correspond to different shoe-sizes.

79. In a shoe machine, a support for shoe-portions movable to different operating positions, operating mechanisms at said positions, a shoe-portion-container having a movable wall and a movable member for locating such shoe-portions at one position for operations upon them at other positions, a member arranged to be set to correspond to different shoe-sizes, and connections to the member arranged to move the container-wall, the locating member and an element of an operating mechanism at another position.

80. The combination with a support having a movable pin and revoluble through a plurality of operating positions, of a variable member for moving the pin, a table at one position provided with a movable wall, a container delivering to the table and having a movable wall, operating mechanism at another position having a variable element, and operator-controlled means arranged to vary the pin-moving member, walls and element simultaneously.

81. The combination with a support having a movable pin and revoluble through a plurality of operating positions, of a variable member for moving the pin, a table at one position provided with a movable wall, a container delivering to the table and having a movable wall, operating mechanism at another position having a variable element, and operator-controlled means arranged to vary the pin-moving member, walls and element in accordance with different sole-sizes.

82. In a shoe machine, means for engaging a shoe-portion at opposite sides to position it laterally, a gage member, and means for moving the engaging means and thereby carrying the portion between them against the gage member.

83. In a shoe machine, means for engaging a shoe-portion at opposite sides to position it, a gage member, and a member fixed relatively to the engaging means for moving said engaging means and carrying the portion between them against the gage member.

84. In a shoe machine, means for engaging a shoe-portion at opposite sides to position it

laterally, a gage member, and means for moving the engaging means and thereby the portion between them against the gage member, said gage member being constructed and arranged to vary the angular position of the portion by contact with it under the influence of the opposite engaging means.

85. In a shoe machine, means for engaging a shoe-portion at opposite sides to position it laterally, a gage member, means for moving the engaging means past the thus-engaged portion, and means made effective in the travel of the engaging means for moving said means and with it the engaged portion toward the gage member.

86. In a shoe machine, a table upon which a shoe-portion is to be positioned, members for engaging the portion at opposite sides of the table, a gage-wall rising from the table, and means contacting with the members to move them toward the portion, vertically past said portion and toward the gage-wall.

87. The combination with a support upon which an operation is to be performed on a sole-portion, of a table, a gage-wall associated with the table and bearing a definite relation to the support, an actuating member, sole-portion-positioning fingers movable upon the actuating member toward and from each other and toward and from the gage-wall, means for moving the actuating member and fingers, means engaged by the fingers in their movement with the actuating member for carrying them toward and from the gage-wall, and means for transferring a positioned portion from the table to the support.

88. The combination with a support upon which an operation is to be performed on a sole-portion, of a table, a gage-wall associated with the table and bearing a definite relation to the support, an actuating member, sole-portion-engaging fingers movable upon the actuating member toward and from each other and toward and from the gage-wall, means for moving the actuating member and fingers vertically, a fixed member engaged by the fingers in their vertical movement with the actuating member for carrying them toward and from the gage-wall, and means for transferring a positioned portion from the table to the support.

89. In a shoe machine, a transferring device movable between a shoe-portion-engaging position and a shoe-portion-disengaging position, a pressure member movable upon the device and set in the movement of said device at one position, means for temporarily retaining the member thus set, and means for releasing the member at another position.

90. In a shoe machine, a transferring device movable between a shoe-portion-engaging position and a shoe-portion-disengaging position, a pressure member movable upon the device and set in the movement of said

device at the engaging position, means for temporarily retaining the member thus set, and means for releasing the member at the disengaging position.

91. The combination with a transferring device movable between engaging and delivering positions, of a pressure member movable upon the transferring device, a contact member at the engaging position arranged to set the pressure member in preparation for its action, and a contact member arranged to release the pressure member for action at the delivering position.

92. In a shoe machine, a transferring device provided with a projection constructed and arranged to enter a shoe-portion, means for moving the projection to prepare it for its separation from the shoe-portion, a pressure member movable upon the device when the projection enters the portion, means for latching the member in the position to which it is moved, and means acting upon movement of the projection for releasing the member to facilitate by its pressure the separation of the portion from the device.

93. In a shoe machine, a traveling transferring device for shoe-portions, a pressure member movable upon the device, means acting in the travel of the transferring device for latching the pressure member in the position to which it is moved, and means for unlatching the pressure member in the travel of the transferring device.

94. In a sole-assembling machine, separated supports, a transferring device movable between the supports, a pressure member movable upon the device at one of the supports, a latch arranged to retain the pressure member temporarily as it is thus moved, and a member at the other support acting upon the latch to release the member.

95. In a sole-assembling machine, separated supports, a transferring device movable between the supports, a pressure member movable upon the device at one of the supports, a spring compressed in such movement, means for temporarily holding the spring compressed, and means at the other support for releasing the member to allow the spring to act.

96. In a shoe machine, a rotatable turret, a support mounted upon the turret, a mechanism into co-operation with which the support is moved by the turret, a sectional driving shaft for operating the mechanism, a clutch member secured to each shaft-section, a dog movable upon one section for engagement with the other, and a member movable in the rotation of the turret and arranged to actuate the dog.

97. In a sole-assembling machine, a rotatable turret, a sole-support mounted upon the turret, a plurality of mechanisms for operating upon the soles presented by the support in the rotation of the turret, a sectional driving

shaft for an operating mechanism, a clutch member secured to each shaft-section, one of said members being provided with a depression, a dog movable upon the other section for engagement with the depression, and a member movable for each sole operated upon and arranged to actuate the dog.

98. In a shoe machine, a rotatable turret, a support mounted upon the turret, a plurality of operating mechanisms into co-operation with which the support is moved by the turret, a sectional driving shaft for an operating mechanism, a clutch member secured to each shaft-section, a dog movable upon one section for engagement with the other, and a member movable in the rotation of the turret and provided with a cam-surface and a stop-surface arranged to act upon the dog.

99. In a shoe machine, a rotatable turret, a support mounted upon the turret, a plurality of operating mechanisms into co-operation with which the support is moved by the turret, a sectional driving shaft for an operating mechanism, a clutch member secured to each shaft-section, a dog movable upon one section for engagement with the other, and a member movable under the control of an element included in the operating mechanism and arranged to actuate the dog.

100. In a shoe machine, a rotatable turret, a support mounted upon the turret, a plurality of operating mechanisms into co-operation with which the support is moved by the turret, a sectional driving shaft for an operating mechanism, a clutch member secured to each shaft-section, a dog movable upon one section for engagement with the other, and a member movable in the rotation of the turret and under the control of an element included in an operating mechanism and arranged to actuate the dog.

101. In a shoe machine, feeding means movable about an axis, a holder, and a shoe-portion-magazine removable from the holder, there being means for locating the magazine in the holder with one extremity and the corresponding ends of the contained shoe-portions in a definite relation to the axis of the feeding means.

102. In a shoe machine, feeding means movable about an axis, a holder provided with opposite sockets, and a shoe-portion-magazine having opposite projections arranged to enter the sockets, there being means associated with the projections at one extremity of the magazine arranged to locate the ends of the contained shoe-portions in a definite relation to the axis of the feeding means.

103. In a shoe machine, a holder, a shoe-portion-magazine arranged to be supported in the holder for removal therefrom, and means movable into co-operation with the magazine to deliver shoe-portions therefrom, the holder being provided with retain-

ing means arranged to control the delivery of portions from the magazine.

104. In a sole-assembling machine, a holder, a sole-portion-magazine arranged to be supported in the holder for removal therefrom, means movable into co-operation with the magazine to deliver sole-portions therefrom, the holder being provided with retaining means arranged to control the delivery of portions from the magazine, and means arranged to vary the relation of the retaining means to the delivering means.

105. In a sole-assembling machine, a holder provided at one side with a movable gate member, a delivering device rotatable beneath the holder, and a sole-portion-magazine arranged to be supported in the holder for removal therefrom, the holder-gate permitting the sole-portions to be removed one by one from the magazine by the delivering device.

106. In a sole-assembling machine, a holder provided at one side with a plurality of movable gate members, means arranged to adjust said gate members independently of one another, a delivering device rotatable beneath the holder, and a sole-portion-magazine arranged to be supported in the holder for removal therefrom, the holder-gates permitting the sole-portions to be removed one by one from the magazine by the delivering device.

107. In a shoe machine, operating mechanism, a container for shoe-portions, a delivering member movable adjacent to the container and having a plurality of receiving depressions successively co-operating with the container, and a transferring device co-operating with each depression after its registration with the container and movable to and from the operating mechanism.

108. In a shoe machine, operating mechanism, a container for shoe-portions, a delivering member movable beneath the container and having spaced shoe-portion-supporting ribs, and a transferring device movable from between the ribs to the operating mechanism.

109. In a shoe machine, operating mechanism, a container for shoe-portions, a disk rotatable beneath the container and having spaced circular ribs in which are depressions successively co-operating with the container, and a transferring device movable between a depression and the operating mechanism.

110. In a sole-assembling machine, a magazine for curved shank-pieces, and a delivering disk rotatable beneath the magazine and provided with circular ribs to support the shank-pieces, said ribs having between them a space above which lie the points of maximum curvature of the shank-pieces.

111. In a sole-assembling machine, a magazine for shank-pieces, and a delivering disk rotatable beneath the magazine and provided with circular ribs in which are radial slots to receive the shank-pieces.

112. In a sole-assembling machine, a magazine for curved shank-pieces, and a delivering disk rotatable beneath the magazine and provided with circular ribs in which are radial slots to receive the shank-pieces, between which ribs is an annular space lying below the point of maximum curvature of the shank-pieces. 5
113. In a shoe machine, a container for shoe-portions, a disk rotatable to deliver portions from the container, and means constructed and arranged to hold the portions upon the disk during the delivering movement. 10
114. In a shoe machine, a container for shoe-portions, a device movable to deliver portions from the container, a transferring device co-operating with the delivering device, and means constructed and arranged to exert a constant retaining force upon the portions from their contact with the delivering device until their removal by the transferring device. 15
115. In a sole-assembling machine, a shank-piece-container, and a device movable to deliver shank-pieces from the container, said device having a magnet contacting with the delivered shank-pieces. 20
116. In a sole-assembling machine, a shank-piece-container, and a device movable to deliver shank-pieces from the container, said device having spaced magnets between which the shank-pieces are deposited from the container. 25
117. The combination with a container, of a delivering disk rotatable beneath the container, and an annular series of magnetic blocks spaced from one another about the disk and arranged to receive articles from the container between the spaced ends. 30
118. The combination with a container, of a delivering disk rotatable beneath the container, and an annular series of magnetic blocks spaced from one another about the disk and having concentric ribs with radial slots extending through the ribs at the spaces, said slots being arranged to receive articles from the container and retain them under the influence of the magnetic attraction. 35
119. The combination with a container, of a delivering disk rotatable beneath the container, and an annular series of magnetic blocks spaced from one another about the disk and arranged to receive articles from the container between the spaced ends, said ends being oppositely inclined from their outer sides toward the center. 40
120. In a shoe machine, a container for shoe-portions, and a delivering member movable in co-operation with the container and having a plurality of shoe-portion-supporting blocks with spaces between their adjacent ends, each of said ends being oppositely inclined from the outer walls of the blocks toward the centers thereof. 45
121. In a shoe machine, a container for shoe-portions, and a delivering member movable in co-operation with the container and having a plurality of shoe-portion-supporting blocks with spaces between their adjacent ends, each of said ends being oppositely inclined from the outer walls of the blocks toward the centers thereof, the inclined ends of adjacent blocks being parallel to each other. 50
122. The combination with a container for shoe-portions, of a delivering disk rotatable beneath the container and having an annular series of supporting blocks with V-shaped spaces between their adjacent ends. 55
123. In a shoe machine, a container for shoe-portions, a member movable beneath the container and having means arranged to successively co-operate with the container to receive shoe-portions therefrom and to there-after deliver them, and an ejecting member co-operating with the receiving means of the movable member after the delivery of the portions therefrom. 60
124. In a shoe machine, a container for shoe-portions, a disk rotatable beneath the container and having a receiving depression, a device co-operating with the depression to transfer a received portion therefrom, and an ejecting member co-operating with the disk between the transferring device and container in the direction of advance of the depression. 65
125. In a shoe machine, a container for shoe-portions, a disk rotatable beneath the container and having a receiving depression, a device co-operating with the depression to transfer a received portion therefrom, and a fixed ejecting member overhanging the disk and inclined downwardly and outwardly therefrom. 70
126. In a shoe machine, a device for transferring shoe-portions from one point to another in the machine, and means arranged at the delivery point and acting upon the transferring device for changing the position at which different portions are deposited. 75
127. In a shoe machine, a device for transferring shoe-portions from one point to another in the machine, and means acting upon the transferring device at a portion only of its travel for changing the position at which different portions are deposited. 80
128. In a shoe machine, a support for shoe-portions, a device for transferring a portion to the support, and means arranged to be set in accordance with shoe-sizes and to change the relation of the transferring device to the support. 85
129. In a shoe machine, a support for shoe-portions, a device for transferring a portion to the support, and a member into co-operation with which the transferring device moves and arranged to change the relation of the transferring device to the support. 90

130. In a shoe machine, a support for shoe-portions, a device for transferring portions to the support and including a carrier and shoe-portion-engaging means movably mounted thereon, and means for moving the engaging means bodily upon the carrier during the transfer of the shoe-portion. 5
131. In a shoe machine, a support for shoe-portions, a device for transferring portions to the support and including a carrier and shoe-portion-engaging means movably mounted thereon, and means for moving the engaging means upon the carrier to change the relation of the transferred portion longitudinally of the support. 10
132. In a shoe machine, a transferring device movable between receiving and delivering points and including a carrier and shoe-portion-engaging means movably mounted thereon, and means situated near the delivering point for moving the engaging means upon the carrier. 15
133. In a shoe machine, a transferring device movable between receiving and delivering points and including a carrier and shoe-portion-engaging means movably mounted thereon, and means situated near both points to move the engaging means upon the carrier. 20
134. In a shoe machine, a movable transferring device including a carrier and shoe-portion-engaging means movably mounted thereon, means for moving the engaging means upon the carrier to an unvarying position, and means for thereafter moving the engaging means upon the carrier to a varying position. 25
135. In a shoe machine, a transferring device movable between receiving and delivering points, means for effecting a setting of the transferring device, and means for applying a correction to the setting. 30
136. The combination with a support, of a carrier movable toward and from the support, a slide movable upon the carrier, an engaging member mounted upon the slide, and a member into contact with which the slide is moved by the carrier and arranged to determine the position of the engaging members relatively to the support. 35
137. The combination with a support, of a carrier movable toward and from the support, a slide movable upon the carrier, an engaging member mounted upon the slide, a member into contact with which the slide is moved by the carrier and arranged to determine the position of the engaging members relatively to the support, and means arranged to set said contact member to vary its effect upon the slide. 40
138. The combination with a support, of a container, a carrier movable between the support and container, a slide movable upon the carrier, an engaging member mounted upon the slide, and contact members associ- 45
- ated with the support and container and arranged to move the slide in opposite directions. 50
139. The combination with a support, of a container, a carrier movable between the support and container, a slide movable upon the carrier, an engaging member mounted upon the slide, contact members associated with the support and container and arranged to move the slide in opposite directions, and means arranged to set the member at the support in different slide-actuating positions. 55
140. In a shoe machine, a support for shoe-portions, a shoe-portion-engaging member movable upon the support, means for delivering a shoe-portion upon the support in engagement with the member, and means arranged to change during the travel of the portion and to correspond to the location of the engaging member the position in which said portion is placed upon the support. 60
141. In a shoe machine, a support for shoe-portions, a shoe-portion-engaging member movable upon the support, means for delivering a shoe-portion to the support, means to superpose another shoe-portion upon the already delivered portion and in engagement with the member, and means arranged to change the position in which the superposed portion is placed upon the support. 65
142. In a sole-assembling machine, a sole-support provided with a movable projection arranged to be set at different points, means for delivering a sole to the support, means for delivering a shank-piece to the support in engagement with the projection, and means arranged to change the point of delivery of the shank-piece to correspond to the setting of the projection. 70
143. In a shoe machine, a support for shoe-portions, an engaging member movable thereon, variable means co-operating with the support for transferring a shoe-portion, and means common to both arranged to vary the engaging member and transferring means. 75
144. In a shoe machine, a support for shoe-portions, an engaging member movable thereon, variable means for transferring a shoe-portion into engagement with the member, and means arranged to be set by the operator to provide simultaneously for a variation in the engaging member and transferring means. 80
145. In a shoe machine, a support for shoe-portions, an engaging member movable thereon, variable means for transferring a shoe-portion into engagement with the member, and means arranged to vary the engaging member and transferring means in accordance with different shoe-sizes. 85
146. In a shoe machine, a variable container for shoe-portions, means for delivering portions from the container, variable means for transferring shoe-portions to the delivered portions, and means common to 90
- 130 95
- 140 100
- 145 105
- 144 110
- 145 115
- 146 120
- 145 125
- 146 130

the container and transferring means for controlling their variation.

147. In a shoe machine, a support for shoe-

5 portions, variable means for applying a liquid-coating to a supported portion, variable transferring means co-operating with the support, and means common to the applying means and transferring means for controlling their variation.

10 148. In a shoe machine, a support for shoe-
portions, variable means for applying a liquid-coating to a supported portion, variable means for transferring shoe-portions to the coated portions, and means common to the applying means and transferring means for controlling their variation.

15 149. In a shoe machine, a support movable to a plurality of operating positions, a movable transferring device for shoe-portions co-operating with the support at one position, variable controlling means for the device, variable operating means at another position, a member arranged to be set by the operator, and connections from such member to the controlling and operating means.

20 150. In a sole-assembling machine, a rotatable turret, a plurality of sole-supports movable to successive positions, variable operating mechanisms at different positions, a device movable to transfer sole-portions to a support at one of the positions, and a member arranged to be set in accordance with sole-sizes and to correspondingly affect an operating mechanism and the transferring device.

25 151. In a shoe machine, a plurality of containers for shoe-portions, operating mechanism associated with each container, means for testing the contents of one of the containers, and means governed by the testing means for controlling the operation of the mechanism of another container.

30 152. In a shoe machine, a plurality of containers for shoe-portions, operating mechanism associated with each container, means for testing the contents of different containers, and means governed by the testing means of different containers for controlling the operation of an operating mechanism.

35 153. In a shoe machine, a plurality of containers for shoe-portions, operating mechanism associated with each container, means for testing the contents of different containers, and fluid-pressure means governed by the testing means of different containers for controlling the operation of an operating mechanism.

40 154. In a shoe machine, a plurality of containers for different shoe-portions, mechanism associated with the containers for assembling the different shoe-portions in a pre-determined relation, and means governed by the contents of a container for controlling a mechanism acting earlier in the assembling cycle than does the mechanism at the governing container.

155. In a shoe machine, a support movable to a plurality of successive operating positions, a container at each position for a shoe-portion different from those at other positions, mechanism at each position for transferring portions from the container to the support, means arranged to test the contents of a container, and means governed by said testing means for stopping the operation of the mechanism at a container the contents of which are earlier transferred.

156. In a sole-assembling machine, a support movable to a plurality of successive operating positions, a sole-container at one position, a container for shank-pieces at a succeeding position, transferring mechanisms operable between the container and support, means for testing the shank-pieces in their container, and means governed by the testing means for stopping the action of the transferring mechanism at the sole-container.

157. In a sole-assembling machine, a support movable to a plurality of successive operating positions, a sole-container at one position, a container for shank-pieces at a succeeding position, transferring mechanisms operable between the containers and support, testing mechanism associated with the sole-container, testing mechanism associated with the shank-piece-container, and means governed by the testing mechanisms of both containers for stopping the action of the transferring mechanism at the sole-container.

158. In a shoe machine, the combination with a container for a stack of shoe-portions, of delivering means movable in co-operation with the container, a testing finger co-operating with the stack, means for forcing the finger toward the stack, the delivering means being organized to permit intermittent contact of the finger with the stack, and means governed by the finger for controlling the machine.

159. In a shoe machine, the combination with a container for a stack of shoe-portions, of a delivering disk rotatable beneath the container, a testing finger co-operating with the stack, a spring arranged to urge the finger toward the stack, the effect of the spring being governed by the disk in its rotation, and means governed by the finger for controlling the machine.

160. In a sole-assembling machine, a sole-support movable through successive positions, a device for transferring a shank-piece upon the support at one position, means for operating upon the supported shank-piece at another position, and connections between the positions governed at the transferring position and controlling the operating means.

161. In a sole-assembling machine, a sole-support movable through successive positions, a device for transferring a shank-piece upon the support at one position, a device for

transferring a filler-piece at another position, and connections governed by the shank-piece-transferring device for controlling the filler-piece-transferring device.

5 162. In a shoe machine, a support for shoe-portions movable to a plurality of operating positions, containers for shoe-portions situated at different positions, and means arranged to vary simultaneously the dimensions of the containers.

10 163. In a shoe machine, a support for shoe-portions movable to a plurality of operating positions, containers for shoe-portions situated at different positions and each having a 15 movable wall, a member arranged for manipulation by the operator and connections between the member and movable walls at different positions.

164. In a sole-assembling machine, operating means, a variable sole-container and a variable filler-piece-container associated with the operating means, setting means graduated in accordance with shoe-sizes, and connections between the setting means and sole 25 and filler-piece-containers.

165. In a shoe machine, a support for shoe-portions movable to a plurality of operating positions, a container for filler-pieces at one position, variable operating mechanism at another position, and means common to both for varying the operating mechanism and the dimensions of the container.

166. In a sole-assembling machine, a support for sole-portions, said support having 35 an engaging projection movable thereon, a variable member for moving the projection, a container for filler-pieces, said container having a variable filler-piece-engaging member and means arranged to vary both members simultaneously.

167. In a sole-assembling machine, a support for sole-portions, said support having an engaging projection movable thereon, a container for sole-portions in which are 45 depressions, said container having a movable bar arranged to engage the depressions, a member for manipulation by the operator, and connections to the member arranged to simultaneously determine the position of the 50 support-projection and of the container-bar in accordance with different shoe-sizes.

168. In a sole-assembling machine, a sole-support having a surface which is approximately a mean between various sizes of right 55 and left soles to be operated upon, means for delivering a sole to the support, means for applying an adhesive to the supported sole, means for placing a sole-portion upon the coated surface of the sole, and a head having a pressure-surface of yieldable material co-operating with the support-surface and corresponding thereto in form, the yieldability of said material rendering it capable of conforming to different sizes of right and left 60 soles.

169. In a shoe machine, a support for shoe-portions, a pressure-head co-operating with the support and having a recess, a pressure-block provided with a stem arranged to enter the recess and having a transverse bore, a 70 plunger movable upon the head through the recess and having a portion arranged to engage the bore in the stem, and a spring maintaining the normal engagement of the plunger and bore. 75

170. In a shoe machine, a delivering member for shoe-portions, and a member for operating upon the delivered portions and having means movable upon the operating member independently of movement of said member into retaining engagement with the shoe-portions. 80

171. In a shoe machine, a pressure-head, a delivering member for shoe-portions movable into co-operation with the head, and a 35 retaining member movable upon the head independently of movement of said head into engagement with a shoe-portion on the delivering member.

172. In a shoe machine, a support for shoe-portions, a pressure member co-operating therewith, a shoe-portion-delivering member movable between the support and pressure member, and impaling members movable upon the pressure member against a shoe-portion on the delivering member. 35

173. In a shoe machine, a delivering member for shoe-portions, a member for operating upon the delivered portions and having means movable upon the operating member into retaining engagement with the shoe-portions, means for holding the retaining means in a normal inactive position, and means under the control of the delivering member for releasing the retaining means. 100 105

174. In a shoe machine, a support for shoe-portions, a pressure member co-operating therewith, a shoe-portion-delivering member movable between the support and pressure member, impaling members movable upon the pressure member against a shoe-portion on the delivering member, latches for the impaling members, and means actuated by the delivering member in its movement for releasing the latches. 110 115

175. In a shoe machine, a support for shoe-portions, a pressure-head movable toward and from the support, a delivering plate movable between the support and head, and a plunger movable upon the head into retaining engagement with a shoe-portion on the delivering plate. 120

176. In a shoe machine, a support for shoe-portions, a pressure-head movable toward and from the support, a delivering plate movable between the support and head, a plunger movable upon the head into retaining engagement with a shoe-portion on the delivering plate, a latch arranged to maintain the plunger normally inactive, and contact means 125 130

actuated by the delivering plate for releasing the latch.

177. In a shoe machine, a support for shoe-portions, a pressure member co-operating therewith, a shoe-portion-delivering member movable between the support and pressure member, impaling members movable upon the pressure member against a shoe-portion on the delivering member, a latch arranged to maintain each impaling member normally inactive, and means common to plural latches for releasing them.

178. In a shoe machine, a support for shoe-portions, a pressure member co-operating therewith, a shoe-portion-delivering member movable between the support and pressure member, impaling members movable upon the pressure member against a shoe-portion on the delivering member, a latch arranged to maintain each impaling member normally inactive, means common to plural latches for releasing them, and yieldable connections between each latch and the releasing means.

179. In a sole-assembling machine, a sole-support, a pressure-head movable toward and from the support, a filler-piece-delivering plate movable between the support and head, plungers mounted upon the head and provided with points for engagement with a delivered filler-piece, a detent for each plunger movable upon the head, and actuating means for the detents having an element lying in the path of the delivering plate.

180. In a sole-assembling machine, a sole-support, a pressure-head movable toward and from the support, a filler-piece-delivering plate movable between the support and head, plungers mounted upon the head and provided with points for engagement with a delivered filler-piece, a detent for each plunger movable upon the head, a rod arranged to reciprocate upon the head, a spring interposed between the rod and each detent, and a lever acting upon the rod and lying in the path of the delivering plate.

181. In a shoe machine, a movable delivering member having a surface upon which shoe-portions may rest and in which surface is a depression, and an operating member co-operating with the delivering member and provided with shoe-portion-impaling means arranged to enter the depression.

182. In a shoe machine, a movable delivering plate having a depression, a pressure member co-operating with the plate, and a plunger movable upon the pressure member and provided with a point arranged to enter a shoe-portion over the plate-depression.

183. In a shoe machine, a reciprocating delivering plate having a movable section with a groove extending in the direction of movement, a pressure-head co-operating with the plate, and a plunger movable upon the head

and provided with a point arranged to pass through a shoe-portion into the groove.

184. In a shoe machine, the combination with a movable delivering member for shoe-portions, of means arranged to be forced 70 against a shoe-portion upon the delivering member and retain said portion, and a relatively fixed member into engagement with which the delivering member moves, said fixed member being arranged to resist the 75 pressure of the retaining means.

185. In a shoe machine, the combination with a movable delivering plate for shoe-portions, of retaining means arranged to be forced against a shoe-portion upon 80 the plate, and a member situated near an end of the path of movement of the plate and provided with an inclined surface for engagement by said plate and with an adjacent surface upon which the 85 plate is guided.

186. In a shoe machine, the combination with a movable delivering plate for shoe-portions, of a pressure-head co-operating 90 with the plate and having a spring-actuated plunger arranged to impale a shoe-portion on the plate, and supporting means into engagement with which the plate moves.

187. In a shoe machine, a support for shoe-portions, a pressure member for co-operation with the support, a delivering member movable between the support and pressure member, a retaining member movable upon the pressure member for engagement with a shoe-portion on the delivering member, and a member arranged to strip the portion from the retaining member upon co-operation between the pressure member and support.

188. In a shoe machine, a support for shoe-portions, a pressure member co-operating 105 with the support, a delivering member movable between the support and pressure member, a plunger movable upon the pressure member and having a shoe-portion-entering point, and a yieldable sleeve surrounding and normally extending beyond the point of the plunger for engagement with a shoe-portion.

189. In a shoe machine, a support for a shoe-portion, a pressure member co-operating therewith, means for producing relative movement between the support and member to apply the pressure, and a plurality of successively acting means for controlling such movement.

190. In a shoe machine, a support for a shoe-portion, a pressure member co-operating therewith, means for producing relative movement between the support and member to apply the pressure, a plurality of devices for controlling such movement, means for actuating one of said devices at regular intervals, and means acting upon a sole-portion and arranged to operate another 125 of the devices.

191. In a shoe machine, a support for a shoe-portion, mechanism for operating upon a shoe-portion, a pressure member co-operating with the support, means for producing relative movement between the support and member to apply the pressure, and means depending for its actuation upon the completion of an operation upon a shoe-portion for controlling such movement. 5
192. In a shoe machine, a support for a shoe-portion, a pressure member co-operating therewith, means for producing relative movement between the support and member to apply the pressure, shoe-portion-engaging means co-operating with the support, automatic means for imparting the engaging movement to said means, and means governed by the engaging means for controlling the pressure-movement. 10
193. In a shoe machine, a support for a shoe-portion, a pressure member co-operating therewith, means for producing relative movement between the support and member to apply the pressure, means for delivering a shoe-portion to receive the pressure, and means dependent upon the position of the delivering means for controlling the pressure-movement. 15
194. In a shoe machine, a support for a shoe-portion, a pressure member co-operating therewith, means for producing relative movement between the support and member to apply the pressure, means for delivering a shoe-portion to receive the pressure, means acting invariably in the operation of the machine for controlling the pressure-movement, and means operable at the termination of the action of the delivering means for controlling such movement. 20
195. In a shoe machine, a support for shoe-portions, a movable pressure member co-operating therewith, fluid-pressure mechanism for moving the pressure member, a delivering member for shoe-portions movable between the support and pressure member, and a valve actuated by the delivering member for controlling the fluid-pressure mechanism. 25
196. In a shoe machine, a support for shoe-portions, a movable pressure member co-operating therewith, fluid-pressure mechanism for moving the pressure member, a delivering member for shoe-portions movable between the support and pressure member, a valve actuated by the delivering member for controlling the fluid-pressure mechanism, and a power-actuated valve for controlling said mechanism. 30
197. In a shoe machine, a support for shoe-portions, a movable pressure member co-operating therewith, fluid-pressure mechanism for moving the pressure member and including a conduit in which are plural valves, a delivering member for sole-portions movable between the support and pressure member 35
- and arranged to actuate one of the valves, and gearing for operating another of the valves. 40
198. In a shoe machine, a support for shoe-portions, a movable pressure member co-operating therewith, fluid-pressure mechanism for moving the pressure member and including a conduit in which are plural valves, a shoe-portion-delivering plate arranged to reciprocate toward and from the support and into operative relation with one of the valves in its outward movement, and gearing for operating another of the valves. 45
199. In a shoe machine, a support, means for placing a shoe-portion thereon, means for operating upon the supported portion, and means acting upon the portion after the operation to correct its location. 50
200. In a shoe machine, a support movable to a plurality of operating positions, means for placing a shoe-portion on the support in a predetermined location at one position, and correcting means acting upon the portion at another position. 55
201. In a shoe machine, a support, means for placing a shoe-portion in a predetermined location thereon, means for operating upon the supported portion, and positioning means acting upon the portion after the operation. 60
202. In a shoe machine, a support, means for placing a shoe-portion in a predetermined location thereon, means for operating upon the supported portion, positioning means acting upon the portion after the operation, and means for further operating upon the portion. 65
203. In a shoe machine, a support, a container for shoe-portions, means for removing a portion from the container and placing it upon the support in a predetermined position, means for operating upon the thus-positioned portion, means movable into contact with the portion after such operation for repositioning said portion, and means for further operating upon the positioned portion. 70
204. In a sole-assembling machine, a support movable to different operating positions, a container for shoe-portions at one of the operating positions, a transferring device movable between the container and the support, means for retaining a sole-portion upon the support as it is placed by the transferring device, means for operating upon the supported portion at another position, and means for repositioning the portion after the last-mentioned operation. 75
205. In a sole-assembling machine, a support movable to different operating positions, a container for shoe-portions at one of the operating positions, a transferring device movable between the container and the support, means for retaining a sole-portion frictionally upon the support as it is placed by the transferring device, means for operating 80
- 120
- 125
- 130

upon the supported portion at another position, and means arranged to overcome the frictional resistance of the retaining means and to reposition the portion after the last-mentioned operation.

5 206. In a shoe machine, a support movable to a plurality of operating positions, means for placing a shoe-portion on the support in a predetermined location at one position, correcting means acting upon the portion at another position, and means at the last-mentioned position for operating upon the portion.

10 207. In a shoe machine, a movable support for shoe-portions, a movable adjusting member into co-operation with which the support is moved, means for moving the adjusting member into contact with a shoe-portion on the support, and means for operating upon the adjusted portion.

15 208. In a shoe machine, a movable support for shoe-portions, movable adjusting members between which the support is moved, means for moving the members toward each other into contact with a shoe-portion on the support, and means for operating upon the adjusted portion.

20 209. In a shoe machine, a movable support for shoe-portions, a movable adjusting member into co-operation with which the support is moved, means for moving the adjusting member into contact with a shoe-portion on the support, and means for operating upon the adjusted portion during the contact of the adjusting member.

25 210. In a sole-assembling machine, a support, means for delivering a sole to the support, means for adjusting the delivered sole, and means for applying a filler-piece to the adjusted sole.

30 211. The combination with a support having a projection, of means for delivering a sole-portion in which is an opening to the support with the projection in the opening, means movable into engagement with the sole-portion to turn it about the projection, and means for operating upon the thus-adjusted portion.

35 212. The combination with a support having a projection, of means for delivering a sole-portion in which is an opening to the support with the projection in the opening, adjusting members movable against the opposite edges of the portion, and operating mechanism co-operating with the support.

40 213. The combination with a support for shoe-portions, of a contact member engaging a supported portion frictionally, means for adjusting the portion upon the support against the friction of the contact member, and means for operating upon the adjusted portion.

45 214. The combination with a support, of means for delivering an article to the support in a predetermined relation, means for

engaging the delivered article frictionally to retain it upon the support, means for operating upon the delivered article, means for correcting the relation of the article upon the support after the operation, and means for thereafter operating upon the article.

50 215. The combination with a support, of a device for transferring a sole to the support in a predetermined relation, a frictional retaining member for the transferred sole, a device for delivering a shank-piece to the sole upon the support, members movable against the edges of the sole to adjust it on the support after the shank-piece has been applied, and a device for delivering a filler-piece over the shank-piece upon the adjusted sole.

55 216. In a shoe machine, a support for shoe-portions of different widths, adjusting members movable against opposite edges of the portions on said support, yieldable means for moving the members, and means for operating upon the portion on the support upon which it has been adjusted.

60 217. In a shoe machine, a support for shoe-portions of different widths, adjusting members movable against opposite edges of the portions, and means for moving the members and permitting them to yield away from the support during their engagement with the shoe-portions.

65 218. In a shoe machine, a support for shoe-portions of different widths, adjusting members movable against opposite edges of the portions, and fluid-pressure mechanism for actuating the members.

70 219. In a sole-assembling machine, a support having a pin arranged to enter an opening in the heel-end of a sole, members movable against the opposite edges of the forepart of the supported sole, and means for thereafter operating upon the sole.

75 220. In a sole-assembling machine, a support having a pin arranged to enter an opening in the heel-end of a sole, members movable against the opposite edges of the forepart of the supported sole, and means for applying a filler-piece to the sole between the members.

80 221. The combination with a support, of a pressure member co-operating therewith, levers fulcrumed at opposite sides of the member, and means for moving the ends of the levers simultaneously toward the support.

85 222. The combination with a support, of a pressure member co-operating therewith, levers fulcrumed at opposite sides of the member, a cylinder, a piston in the cylinder connected to the levers, and a source of fluid-pressure joined to the cylinder.

90 223. In a shoe machine, mechanism for operating upon shoe-portions, means for adjusting the relation of a portion to be operated on, and means governed by the adjusting means for controlling the operating mechanism.

224. In a shoe machine, mechanism for operating upon shoe-portions, means for adjusting the relation of a portion to be operated on, and means actuated as the adjustment approaches completion for controlling the operating mechanism. 6
225. In a shoe machine, mechanism for operating upon shoe-portions, means for adjusting the relation of a portion to be operated on, and means actuated from the adjusting means as the adjustment approaches completion for controlling the operating mechanism. 10
226. In a shoe machine, a support for shoe-portions, a pressure member co-operating therewith, a member movable into contact with a portion upon the support, and means governed in the movement of the contact member for controlling the pressure member. 15
227. In a shoe machine, a support for shoe-portions, mechanism for operating upon a supported portion, fluid-pressure mechanism for actuating the operating mechanism, a valve arranged to control the fluid-pressure mechanism, an adjusting member movable against the portion on the support, and connections from the adjusting member to the valve. 20
228. In a shoe machine, a support for shoe-portions, mechanism for operating upon a supported portion, fluid-pressure mechanism for actuating the operating mechanism, a valve arranged to control the fluid-pressure mechanism, an adjusting member movable against the portion on the support, and connections from the adjusting member to the valve arranged to open said valve during the movement of the adjusting member. 25
229. In a shoe machine, a support for shoe-portions, a pressure member co-operating therewith, means for producing relative movement between the support and member to apply the pressure, a plurality of devices for controlling such movement, and a plurality of means for successively acting upon a shoe-portion and arranged to operate the devices. 30
230. In a shoe machine, a support for shoe-portions, a pressure member co-operating therewith, means for producing relative movement between the support and member to apply the pressure, a plurality of devices for controlling such movement, means for actuating one of said devices at regular intervals, and a plurality of means for successively acting upon a shoe-portion and arranged to each operate another of the devices. 35
231. In a shoe machine, a support for shoe-portions, a pressure member co-operating therewith, means for producing relative movement between the support and member to apply the pressure, delivering means for shoe portions co-operating with the support, means for adjusting a portion upon the support in preparation for the application of 40
- pressure, and means depending upon the position of the delivering means and adjusting means for controlling the pressure-motion. 45
232. In a shoe machine, a support for shoe-portions, a movable pressure member co-operating therewith, fluid-pressure mechanism for moving the pressure member, a delivering member for shoe-portions movable between the support and pressure member, adjusting members movable against opposite sides of a portion on the support, and valves actuated by the delivering member and adjusting members and successively controlling the fluid-pressure mechanism. 50
233. In a shoe machine, a support for shoe-portions, a movable pressure member co-operating therewith, fluid-pressure mechanism for moving the pressure member, a delivering member for shoe-portions movable between the support and pressure member, adjusting members movable against opposite sides of a portion on the support, valves actuated by the delivering member and adjusting members and successively controlling the fluid-pressure mechanism, and a power-actuated valve for controlling said mechanism. 55
234. In a shoe machine, a support for shoe-portions having different contours, opposite members movable into contact with a portion to adjust it upon the support, and means arranged to modify the movement of both the members to produce their proper operation upon portions differently formed. 60
235. In a sole-assembling machine, a support for right and left sole-portions, and means arranged to move a portion on the support to produce substantial axial alinement between said support and either right or left portions. 65
236. In a shoe machine, a support for right and left shoe-portions, an adjusting member movable into contact with a portion on the support, and means arranged to vary the position of the member to correspond to either a right or a left portion. 70
237. In a shoe machine, a support for shoe-portions differing in form, a movable carrier, adjusting members for the shoe-portions mounted upon the carrier at opposite sides of the support, and means arranged to position the carrier to correspond to the form of the shoe-portion upon the support. 75
238. In a sole-assembling machine, a support for right and left sole-portions, a reciprocating carrier, levers fulcrumed upon the carrier and extending at opposite sides of the support, and means arranged to move the carrier and secure it at either extremity of its path of movement. 80
239. The combination with a support, of a movable carrier, an adjusting member for articles upon the support, a cylinder fixed adjacent to the carrier, a piston operating in the cylinder and connected to the adjust- 85

- 125
- 130

ing member, means arranged to vary the position of the carrier and to secure it against movement, and means for supplying fluid-pressure to the cylinder.

5 240. In a shoe machine, a mechanism for operating upon right and left shoe-portions, a plurality of elements variable in position and arranged to determine the location of right and left shoe-portions in successive positions thereof, and connections between the members arranged to cause the position of one member to correspondingly position another.

10 241. In a shoe machine, a variable container for shoe-portions, a support to which the portions are delivered from the container, and means arranged to vary simultaneously the container and the location of a portion upon the support.

20 242. In a shoe machine, a container for shoe-portions, said container having a movable wall, a support to which the portions are delivered from the container, an adjusting member co-operating with the support, and position-varying connections between the wall and adjusting member.

25 243. In a sole-assembling machine, a container for sole-portions, said container having a wall movable transversely of the longitudinal axes of the contained portions, a support to which a portion is delivered from the container, an adjusting member movable transversely of the axis of the supported portion, and connections arranged to cause the wall and adjusting member to move together.

30 244. In a shoe machine, a container for shoe-portions, said container having a movable wall, a support to which a portion is delivered from the container, a movable carrier, a shoe-portion-adjusting member pivoted, upon the carrier, and connections arranged to cause the wall and carrier to move together.

35 245. In a sole-assembling machine, a container for sole-portions having a wall movable in the direction of the longitudinal axes of the contained portions, a wall movable transversely of said axes, means arranged to determine the position of the first-mentioned wall in accordance with shoe-sizes, means arranged to determine the position of the companion wall according to whether a portion of a right or a left sole is to be held, a movable member co-operating with the container, and position-varying connections between said member and one of the walls.

40 246. In a sole-assembling machine, a container for sole-portions having a wall movable in the direction of the longitudinal axes of the contained portions, a wall movable transversely of said axes, means arranged to determine the position of the first-mentioned wall in accordance with shoe-sizes, means arranged to determine the position of the companion wall according to whether

50 a portion of a right or a left sole is to be held, a support to which the portions are delivered from the container, a movable adjusting member co-operating with the support, and position-varying connections between the transversely movable wall and adjusting member.

55 247. In a sole-assembling machine, a support movable to a plurality of successive operating positions, transferring mechanism at each position, a sole-container at one position, a container at a succeeding position from which a filler-piece is delivered to a sole upon the support, means for testing the filler-pieces in their container, and means governed by the testing means for stopping the action of the transferring mechanism at the sole-container.

60 248. In a sole-assembling machine, a support movable to a plurality of successive operating positions, transferring mechanism at each position, a sole-container at one position, a container at a succeeding position from which a filler-piece is delivered to a sole upon the support, testing mechanism associated with the sole-container, testing mechanism associated with the filler-piece-container, and means governed by the testing mechanism of both containers for stopping the action of the transferring mechanism at the sole-container.

65 249. In a sole-assembling machine, a support movable to a plurality of successive operating positions, transferring mechanism at each position, a sole-container at one position, a container at a succeeding position from which a shank-piece is delivered to a sole upon the support, a container at still another position from which a filler-piece is delivered to the sole and shank-piece on the support, testing mechanism associated with each of the three containers, and means governed by the condition of all of the containers for stopping the action of the transferring mechanism at the sole-container.

70 250. In a shoe machine, the combination with a plurality of containers for shoe-portions, testing members movable to engage the portions in the respective containers, and mechanism associated with one of the containers and arranged to produce the testing movements at plural containers.

75 251. In a shoe machine, the combination with a plurality of containers for shoe-portions, testing members movable to engage the portions in the respective containers, and a delivering member co-operating with one of the containers, said delivering member being constructed and arranged to govern the testing movement at its container and at an associated container.

80 252. In a sole-assembling machine, a magazine for a stack of shank-pieces, a magazine for a stack of filler-pieces, a stack-testing member movable into and out of contact with

the stack in each magazine, and a delivering member co-operating with one of the magazines and being provided with means arranged to govern the testing movement at both magazines.

253. In a sole-assembling machine, a magazine for a stack of shank-pieces, a magazine for a stack of filler-pieces, a stack-testing finger arranged to move adjacent to each stack, and a delivering disk rotatable beneath the shank-piece-magazine and provided with means for governing the movement of both fingers.

254. In a shoe machine, the combination with a support provided with projection arranged to enter an opening in a shoe-portion to be supported, of a transferring device cooperating with the support and having grasping members arranged to engage a supported portion at points removed from the projection and provided with a member arranged to engage said portion in close proximity to the projection.

255. In a shoe machine, the combination with a support for shoe-portions, of a transferring device co-operating with the support and having a movable shoe-portion-engaging member, means for governing the position of said member and a member for grasping a portion, said member being controlled by the governing means.

256. In a shoe machine, the combination with a support provided with a projection arranged to enter an opening in a shoe-portion to be supported, of a transferring device co-operating with the support and having members arranged to engage a supported portion at points removed from the projection and movable relatively to each other to grasp and release the supported portion, means for governing the position of said members and an additional member for grasping the portion, said member being controlled by contact with the governing means.

257. In a shoe machine, the combination with a support provided with a projection arranged to enter an opening in a shoe-portion to be supported, of a transferring device co-operating with the support and having members arranged to engage a supported portion at points removed from the projection and movable relatively to each other to grasp and release the supported portion, a latch arranged to temporarily retain said member in its engaged relation and a shoe-portion-grasping member movable under the influence of the latch.

258. In a sole-assembling machine, the combination with a support provided with a pin arranged to enter an opening near one extremity of a sole upon the support, of a transferring device co-operating with the support and having fingers arranged to engage the under portion of the supported sole

at opposite sides and a member arranged to engage the under side of the sole at the end adjacent to the opening.

259. In a sole-assembling machine, the combination with a support provided with a pin arranged to enter an opening near one extremity of a sole upon the support, of a transferring device co-operating with the support and having fingers arranged to engage the under portion of the supported sole at opposite sides, a latch for the fingers and a member arranged to engage the under side of the sole at the end adjacent to the opening and contacting with the latch.

260. In a shoe machine, the combination with a support for shoe-portions, of a carrier movable toward and from the support, a shoe-portion-engaging member mounted to oscillate upon the carrier, and a contact member arranged to swing the engaging member in its movement to a predetermined position with relation to the support.

261. In a shoe machine, the combination with a support provided with a variable element for engagement with a shoe-portion, of a carrier movable toward and from the support, a shoe-portion-engaging member mounted to oscillate upon the carrier, a contact member arranged to swing the engaging member in its movement, and means arranged to position the contact member to correspond to the location of the engaging element of the support.

262. In a shoe machine, the combination with a support for shoe-portions, of a carrier movable toward and from the support, a shoe-portion-engaging member mounted to move upon the carrier, and a guideway having opposite walls receiving between them an element movable with the engaging member.

263. In a shoe machine, the combination with a support for shoe-portions, of a carrier movable toward and from the support, a shoe-portion-engaging member mounted to move upon the carrier, a device constructed and arranged to frictionally retain the engaging member in the position to which it is moved, and a guideway having a tapering throat to receive an element movable with the engaging member.

264. In a shoe machine, the combination with a support for shoe-portions, of a carrier movable toward and from the support, a shoe-portion-engaging member mounted to move upon the carrier, a guideway having opposite walls receiving between them an element movable with the engaging member, and means arranged to vary the position of the guideway.

265. In a shoe machine, the combination with a support for shoe-portions, of a parallel motion mounted to oscillate into and out of co-operation with the support, a bar pivoted upon an element of the parallel motion, a retaining device connecting said element

and bar, shoe-portion-engaging means carried by the bar, and a variable contact member arranged to act upon the bar in the oscillation of the parallel motion.

266. In a shoe machine, a support provided with a variable element arranged to engage a shoe-portion, a movable transferring device arranged to grasp the shoe-portion on the support adjacent to the variable element, and means common to the support-element and transferring device for varying the former and altering the travel of the latter.

267. In a shoe machine, a support for shoe-portions, a shoe-portion-engaging member movable upon the support, movable grasping means for removing a shoe-portion from the support, and means arranged to change during the travel of the removing member and to correspond to the location of the engaging member the point at which the removing means grasps a sole-portion on the support.

268. In a sole-assembling machine, a sole-support provided with a movable projection arranged to be set at different points, removing means for grasping a sole on the support, and means arranged to change the point at which the removing means grasps the sole to correspond to the setting of the projection.

269. In a shoe machine, a support for shoe-portions, an engaging member movable thereon, variable means for moving the member, variable transferring means for grasping a shoe-portion upon the support adjacent to the engaging member, and means common to both arranged to vary the moving means and transferring means.

270. In a shoe machine, a support for shoe-portions, an engaging member movable thereon, a variable member for moving the engaging member, variable transferring means for grasping a shoe-portion upon the support adjacent to the engaging member, and means arranged to vary the moving member and transferring means in accordance with different shoe-sizes.

271. In a shoe machine, a support for shoe-portions, variable means for transferring shoe-portions to the support, variable means for transferring work from the support, and means common to the transferring means for controlling their variation.

272. In a sole-assembling machine, a rotatable turret, a plurality of sole-supports movable to successive positions, variable operating mechanisms at different positions, a device movable to transfer sole-portions to a support at one of the positions, a device movable to transfer soles from the support at another position, and a member arranged to be set in accordance with sole-sizes and to correspondingly affect an operating mechanism and the transferring devices.

273. In a shoe machine, a support for shoe-

portions, variable means for applying a liquid-coating to a supported portion, a receptacle for the work, variable means for transferring the work from the support to the receptacle, and means common to the applying means and transferring means for controlling their variation.

274. In a shoe machine, a support for shoe-portions, variable means for applying a liquid-coating to a supported portion, variable means for transferring shoe-portions to the coated portions, a receptacle for the work, variable means for transferring the work from the support to the receptacle, and means common to the applying means and transferring means for controlling their variation.

275. In a shoe machine, a movable support for shoe-portions, a member movable with the support, operating mechanism into co-operation with which the support moves, said operating mechanism being controlled by the support member, and means engaged by the support member for positioning the support.

276. In a shoe machine, a support for shoe-portions movable to a plurality of operating positions, a member movable with the support, operating mechanism at a position controlled by the support member, and support-locating means engaged by the member at another position.

277. The combination with a rotatable turret, of a plurality of supports mounted thereon and movable to successive operating positions, a member associated with each support, mechanism at operating positions controlled successively by the support members, and a turret-locating device at another position engaged by said members.

278. In a shoe machine, a support carrying a movable shoe-engaging member, a variable device for adjusting the engaging member, variable operating mechanism associated with the support, and means common to both for varying the device and mechanism.

279. In a shoe machine, a support movable to different operating positions and carrying a movable shoe-portion-engaging member, a variable device arranged to adjust the engaging member in the movement of the support, variable operating mechanism at a position, and means common to both for varying the device and mechanism.

280. In a shoe machine, a support movable to different operating positions and carrying a movable shoe-portion-engaging member, a variable device arranged to adjust the engaging member in the movement of the support, variable operating mechanisms at succeeding positions, and means arranged to vary simultaneously the device and a plurality of the operating mechanisms.

281. In a shoe machine, a support movable to different operating positions and carrying a movable shoe-portion-engaging member, a variable device arranged to adjust the en-

gaging member in the movement of the support, variable operating mechanism at a position, a member arranged to be set to correspond to different shoe-sizes, and connections from said member to the device and operating mechanism.

282. In a sole-assembling machine, a support for sole-portions movable to different operating positions and having a movable locating projection, a member arranged to adjust the projection upon the support, mechanism at an operating position arranged to co-operate with the support, a member arranged to be set to correspond to different shoe-sizes, and connections from said member to the support-projection and to an element of the operating mechanism.

In testimony whereof I have signed my name to this specification.

20 SAMUEL R. CUTLER,
Administrator of the Estate of Frederick M.
Furber, Deceased.
